ACCOUNTING MACHINE AND THE LIKE

Robert L. Muller, Detroit, Mich., assignor to Burroughs Adding Machine Company, Detroit, Mich., a corporation of Michigan

Application February 28, 1942, Serial No. 432,813

29 Claims. (Cl. 235—60)

This invention concerns accounting and the like machines, particularly machines having traveling carriages, and relates primarily to a presettable selective carriage return control mechanism for such machines.

A type of work for which such machines are intended involves the posting of lines of entries on columnar forms having at least one column for data, the presence or absence of which, and the character of which, if present, is determined by the character of an entry in the same line in a nonadjacent preceding column. One example of such work is the posting of customers' checking accounts in banks wherein the amount of the old balance is entered in an old balance column at the beginning of a line of postings, then the amount or amounts of one or more checks drawn against the account is or are entered in one or more check columns and/or the amount of a deposit to the account is entered in a deposit column, and the amount of the new balance is printed in a new balance column. The columns are arranged on a main portion of the form from left to right in the order mentioned above.

In present bank practice, it is necessary to produce analyses of customers' checking accounts to determine when and what charges should be made for handling the accounts to prevent loss or insure a predetermined minimum profit for the bank. For example, the portions of the daily balances of customers' accounts which are available for the use of the bank are dependent upon what portions of such balances remain after deducting credited amounts which are in collection and not yet received by the bank. For that purpose, the form is provided with a second new balance column to the right of the main portion of the form and with an analysis column at the right of the second new balance column. On the customer's statement form, a line of perforations may be formed between the two new balance columns to permit the portion containing the second new balance and analysis columns to be detached from the statement before the latter is delivered to the customer.

The data to be posted in the analysis column in any line of postings, in this example of work, is determined from the nature of the entry posted in the deposit column in the same line, and may consist of the amount of any items, such as checks on other banks, which are included in the entry posted in the deposit column but which will not be available for the use of the bank until collected. When no entry is made in the deposit

5 column in a line of posting, or when the entry in the deposit column represents solely currency or checks drawn on the same bank, there will be no entry to be made in the analysis column and time can be saved and the work output of the machine and operator can be increased if the traveling carriage of the machine can be returned to its starting position for a new line of 10 postings immediately after the printing of the new balance in the column preceding the analysis column and without tabulating into the latter column and so requiring the operator to act, as by depressing a motor bar to give the machine a blank operation, to cause the carriage to be 15 returned without an entry being made in the analysis column.

The present invention provides an improved means to permit the machine operator, at the time of operating the machine, to print an entry in the deposit column, or at the time of operating the machine to print an entry in a preceding column in case no entry is to be printed in the deposit column, to control the conditioning of a means to cause the carriage automatically to be 20 returned after the printing of the new balance in the column preceding the analysis column, in case no entry is to be printed in the latter column, or permit the carriage to tabulate to the analysis column if an entry is to be printed there, said 25 means also adapting the machine for other work requiring such a presettable selective control of the carriage return.

An object of the present invention is to provide a machine of the class mentioned above with an 30 improved presettable selective carriage return means.

A further object of the invention is to provide a machine of the class mentioned above with a presettable selective carriage return means of 35 simplified construction and reduced cost.

A further object of the invention is to provide a machine of the class mentioned above with a presettable selective carriage return means which will render the machine adaptable to the greatest 40 number of varieties of work with the minimum of interference with other devices and mechanisms which may be included in the machine for the work involved.

50 A Burroughs high keyboard machine provided with one embodiment of the invention is illustrated by way of example in the accompanying drawings, in which:

Figure 1 is a right side elevation of the machine with the casing removed and with the various parts in their normal positions, a few of the parts

being broken away for clearness of illustration; Fig. 2 is a detail illustration of certain parts of Fig. 1;

Fig. 3 is a left side elevation showing certain operating and control parts located on or near the left side of the machine;

Fig. 4 is a right side view on a large scale of certain parts at the rear of the right side of the machine;

Fig. 5 is a detail illustration of the "Cycle normal" key and certain parts controlled thereby, some of which can be seen also in Fig. 4;

Fig. 6 is a right side elevation of the machine showing certain parts associated more especially with the automatic total mechanism, these parts being shown in the positions they occupy at the time they have just moved to automatic total-taking or subtotal-taking position but before the cycle of operation of the machine has commenced, other parts shown in Fig. 1 being omitted from Fig. 6 for clearness;

Fig. 7 is a detail illustration of certain parts of Fig. 6;

Fig. 8 is a right side view illustrating some of the parts of Fig. 6 in the positions they occupy when an automatic total or subtotal-taking operation is prevented by reason of the crossfooter register not being in a position in agreement with the sign of the total contained in said register;

Fig. 9 is a right side view of the parts shown in Fig. 8 and of some further parts of Fig. 6 in the positions they occupy when an automatic total or subtotal-taking operation has been prevented as in Fig. 6 but after the machine has been given a cycle of operation in which the crossfooter register has been moved to the position corresponding to the sign of the total contained therein;

Fig. 10 is a detail illustration of certain parts shown in Figs. 6 and 9;

Fig. 11 is a left side view of some of the parts which are more particularly concerned with the control of the carriage movements, the parts being shown in their normal positions;

Fig. 12 is a detail perspective view of certain parts controlling the presettable selective return of the carriage.

Fig. 13 is a front elevation of certain parts of the carriage return mechanism;

Fig. 14 is a rear elevation of certain parts of the carriage return mechanism;

Fig. 15 is a perspective view of portions of the improved presettable selective carriage return means as the presettable control parts are being preset for an automatic return of the carriage from a position preceding the last columnar position of the carriage;

Fig. 16 is a perspective view of portions of the improved presettable selective carriage return means as the carriage return from a column preceding the last column is being initiated by the preset control parts;

Fig. 17 is a detail perspective of certain parts of Fig. 16;

Fig. 18 is a vertical section of the parts shown in Fig. 17;

Fig. 19 is a partial rear elevation of the machine with the carriage return means removed to reveal the arrangement and location of carriage controls; and

Fig. 20 is a schematic illustration of an example of work performed by the machine and indicates the relation between the columnar positions of the carriage and the carriage positions

when certain control elements become effective while the machine is set up for the illustrated example of work.

The drawings show an embodiment of this invention as applied to the well-known Burroughs high keyboard machine illustrated in many patents, as, for example, the Pasinski Patents Nos. 1,778,506 and No. 1,911,768, for which reason the general construction of the machine will be described only briefly, reference being had to the foregoing and other issued patents for further details of the general construction. It will be obvious to those skilled in the art that the invention may be applied to other types of calculating machines.

General construction

The illustrated machine may be given cycles of operation by an electric drive motor 25 (Fig. 1) operating through a clutch 26, as described in the Vincent Patent No. 866,750, the motor and clutch being controlled as disclosed in the Bindschedler Patents Nos. 1,658,036 and 1,773,164 from a motor bar M. The front and rear stems of said motor bar M are supported on studs on levers 27 and 28 (Fig. 6) pivoted on shafts 29 and 30, respectively, and having a stud and slot connection 31 with each other between said pivots. The levers 27 and 28 are urged clockwise and counterclockwise, respectively, by a spring 32 connected between said levers and thus urging the motor bar M upward to normal position. The rear end of the lever 27 has a stud 33 (Fig. 10) engaging in a slot in a control link 34. A spring 35 is connected between the lever 27 and the link 34 to urge said link upwardly relatively to said lever and tends to maintain the stud on said lever at the lower end of the slot in said link. The lower end of the link 34 passes through an opening in a stud 36 pivotally secured in the end of an arm 37 through which the usual clutch and motor switch are controlled as shown in said Bindschedler patents. A spring 34a surrounding the link 34 and compressed between a shoulder on said link and the arm 36 urges the link and arm upward and downward, respectively, relatively to each other to the limit determined by nuts threaded on the lower end of the link.

Depression of the motor bar M rocks the levers 27 and 28 counterclockwise and clockwise, respectively, and the rear end of lever 27 acting through the spring 35 raises the link 34 and the forward end of the arm 37 to close the motor switch and connect the clutch to give the machine a cycle of operation. The levers 27 and 28 are latched in their rocked positions, as in Fig. 6, to hold the motor bar M depressed, by the usual "repeat hook" or latch 38 which is pivoted on the lever 28 and spring urged clockwise into latching engagement with a stud 39 on the rear arm of the lever 27.

For each cycle, the clutch shaft 40 (Fig. 1) and the crank arm 41 thereon rotate one revolution and, through the link 42, rock an arm 43 first clockwise and then counterclockwise about a shaft 44 on which said arm is freely rockably mounted. The arm 43 has an abutment cooperating with an abutment on an arm 45 secured on the shaft 44 whereby the arm 43 when driven clockwise also drives the arm 45 and shaft 44 clockwise in what is known as the "forward stroke" of the cycle. An arm 46 also secured to the shaft 44 is connected to springs 47 which return the shaft 44 and arms 45 and 46 counter-

clockwise in the "return stroke" of the cycle while the motor, clutch and arm 43 generally run somewhat ahead of the arm 45. The arm 46 is connected through a link 48 (Figs. 1 and 6) to the usual full-stroke sector 49 secured on the shaft 50 to which the usual hand crank may be attached for cycling the machine manually when desired.

The full stroke sector 49 is rocked counterclockwise in the forward stroke and returned clockwise in the return stroke of each machine cycle. The upper rear edge of the full stroke sector 49 is normally engaged by the lower arm of a three-armed lever 55 (Fig. 6) pivoted on a fixed stud 56 and pivotally carrying on the end of its rearward arm two pass-by pawls 57 and 58 (Figs. 4 and 6) urged clockwise by individual springs 59 whereby the three-armed lever 55 is also urged to rock clockwise as the full stroke sector 49 rocks counterclockwise in the forward stroke of a machine cycle. If the three-armed lever 55 is permitted to rock clockwise to the extent of its longest stroke, both pawls 57 and 58 are carried past a roller 60 carried on the lower end of one side arm of the usual keyboard release bail 61 pivoted on a shaft 62 and urged clockwise to the position shown in Figs. 1, 4 and 6 by a spring 63, the springs 59 permitting the pawls 57 and 58 to yield without rocking the bail 61. Then, during the return stroke of the cycle, the full stroke sector 49 returns the three-armed lever 55 counterclockwise to normal, causing the long pawl 58 to cam the roller 60 rearwardly and thereby rocking the bail 61 sufficiently not only to release depressed keys but also to cause the upper end of its right-hand side arm to move a slide 64 supported on the lower keyboard plate forwardly against the tension of a spring 64a (Fig. 6) to engage a lateral lug 65 on said slide with an upward projection on the latch 38 and rock the latter to release the levers 27 and 28 whereupon the latter and the motor bar M are restored to normal by the spring 32. Should the operator continue to hold the regular motor bar M depressed, either directly or through either the upper or the lower motor bar U or L as described later, at and after the time the repeat hook 38 is released from the stud 39 by the projection 65, a detent 66 pivoted on the stud 30 is rocked counterclockwise by a spring 67 to position a shoulder 68 on the upper one of two rearwardly extending arms thereof in front of a stud 69 on the repeat hook 38 to hold the latter in releasing position until the motor bar M is permitted to restore to normal whereupon the stud 39 in lever 27 depresses the lower arm of the detent 66 to disengage the shoulder 68 from the stud 69.

During the forward stroke of each machine cycle, a stud 70 (Fig. 4) on the full stroke sector 49 engages a projection 71 on the control link 34 and returns the latter downward somewhat below its normal position, thereby carrying a stud 72 on the link 34 below the lower end of a latch pawl 73 pivoted on a fixed stud 74. A spring 75 urges the pawl 73 clockwise to engage a forward projection of said pawl against the stud 39 and to position the lower end of said pawl above the lowered stud 72 to prevent the control link 34 from moving upwardly far enough to initiate another machine cycle as the full stroke sector 49 and stud 70 return to normal in the return stroke of a machine cycle. When the lever 27 returns to normal after release of the latch 38, the stud 39 depresses the forward pro-

jection of the pawl 73 and swings the lower end of said pawl rearwardly of the stud 72 so that the control link 34 is free to rise upon the next depression of the motor bar M.

5 A bell crank 80 (Figs 1 and 4) pivoted on a stud 81 carried by the stem 82 of an upper motor bar U has in its forward arm a slot which receives a stud 83 carried by the rear end of the lever 28. The parts are normally positioned as in Fig. 1. When the regular motor bar M is depressed, the bell crank 80 is rocked counterclockwise to place the end of its lower arm above a fixed squared stud 84 on which the stem 82 is slidably guided, whereby the upper motor bar U is locked against depression until the regular motor bar M returns to normal. When the upper motor bar U is depressed, a stud 85 secured in the stem 82 engages the upper edge of the forward arm of the bell crank 80 to prevent clockwise rocking thereof and thereby causes the regular motor bar M to be depressed with the upper motor bar and latched down by the repeat latch 38. The end of the lower arm of the bell crank is then positioned in front of the stud 84, whereby the upper motor bar U is latched in depressed position until the regular motor bar M returns to normal.

10 The stem 86 (Fig. 1) of a lower motor bar L has an arm 87, the upper rearward end of which is positioned over a stud 88 carried by the forward end of the lever 27 so that depression of the lower motor bar L also causes the regular motor bar M to be depressed and latched down by the repeat latch 38. The slotted end of the upper arm of a bell crank 89 pivoted on a stud 90 secured in the stem 86 receives the stud 88. When the lower motor bar L is depressed, the end of the lower arm of the bell crank 89 is moved down behind a fixed stud 91 whereby the lower motor bar L is latched down until the regular motor bar M returns to normal, but when the motor bar M is depressed without depressing the lower motor bar L, the end of the lower arm of the bell crank 89 is positioned over the stud 45 91 to lock the lower motor bar against depression until the regular motor bar M returns to normal.

15 Thus the upper and lower motor bars U and L, when depressed, initiate machine cycles by causing depression of the regular motor bar M and elevation of the control link 34. They also perform further functions which will be described later.

20 The amount entering means of the illustrated machine comprises a suitable number of rows or banks of keys 95 (Figs. 1 and 3) which, when depressed, rock individual bell cranks 96 which move stop wires 97 into position to arrest the amount actuator sectors 98 (Fig. 1), associated with the several banks or keys, at positions 25 corresponding to the depressed keys 95 in the respective key banks when said actuators descend from their normal positions during the forward stroke of the cycle. During the return stroke, the lowered actuators 98 are raised again to their normal positions by the usual bail (not shown) and the depressed keys 95 are restored to normal.

25 The illustrated machine has a main adding and subtracting totalizer or crossfooter of the "tumbling" type having a plurality of pairs of meshing pinions 99 and 100 (Figs. 1 and 3). This main register or crossfooter is constructed and operated substantially as disclosed in Pasinski Patents 1,778,506 and 1,911,768. The pinions 99 and 100 are supported in a tumbling frame 70 101 (Fig. 3) pivotally supported by studs 102 in

a main frame 103 rockably mounted on the shaft 104. The tumbling frame 101 is normally positioned so that, when it is moved toward the actuators 98, by rocking of the main frame 103 about the shaft 104, the add pinions 99 of each pair of pinions 99 and 100 will mesh with the corresponding actuators but the frame 101 may be tumbled to cause the subtract pinions 100 to mesh with the actuators upon movement of the frame 101 toward the actuators. For amount 10 entering operations, i. e., addition or subtraction, the pinions 99 or 100 are out of mesh with the actuators 98 throughout the descent of the actuators but the pinions are in mesh with the actuators during their return to normal in the return stroke of the amount entering cycle so that amounts entered on the keys 95 will be entered into the register. In total-taking operations, the pinions 99 or 100 are in mesh with the actuators during the forward stroke of the total-taking 20 cycle and the actuators 98 descend until the corresponding pinions are arrested. The pinions are disengaged from the actuators while the latter rise again to their normal positions during the return stroke of the total-taking cycle. In 25 subtotal-taking cycles, the pinions 99 or 100 are meshed with the actuators during both the forward and return strokes so that the total withdrawn from the totalizer in the forward stroke is reentered during the return stroke. In adding, 30 positive total taking and positive subtotal taking, the pinions 99 are meshed with the actuators 98 but, in subtracting, negative total taking and negative subtotal taking, the pinions 100 are meshed with the actuators.

For the add-subtract totalizer 99—100, there is a tens-transfer mechanism effecting both "carries" and "borrows" by means of an extra step of return movement of the actuators 98 beyond their normal positions as disclosed in the Rinsche Patent No. 1,172,484. Portions of this transfer mechanism arrest the totalizer pinions in their positive "0" positions in positive total-taking and positive subtotal-taking operations and in their positive "9" positions in negative total-taking and negative subtotal-taking operations. A "fugitive 1" mechanism also like that disclosed in the Rinsche Patent No. 1,172,484 is provided to enable numerically correct negative as well as positive totals to be obtained.

The illustrated machine also has a multiple register line comprising a plurality of adding registers 105 (Fig. 1) constructed and operated as disclosed in the Pasinski Patent No. 1,911,768 and provided with a tens-transfer mechanism also like that disclosed in said Pasinski patent and in the Pasinski Patent No. 1,774,289. The registers 105 are out of engagement with the actuators 98 while the machine is at rest.

The printing mechanism in the illustrated machine is of the general type disclosed in W. S. Burroughs Patent No. 505,078 and comprises, for each actuator and corresponding bank of keys, a set of printing type 106 (Fig. 1) carried on the rear arm of the lever 107, the forward arm of which carries the actuator 98. Thus, at the end of the forward stroke of a cycle, the types 106 corresponding to the amount entered on the keys 95 or the total or subtotal taken from the cross-footer 99—100 or from a register 105 are positioned at the printing line. These type are then driven by hammers 108 (Fig. 1) against record material held about a platen roller P. The printing hammers are controlled, as in the usual machine of the type illustrated and as disclosed

in various patents, to secure the desired printing in selected orders.

Printing is effected in selected columns on the work sheet, the selection of columns being controlled by columnar printing control means which, in the form provided in the illustrated machine, comprises a traveling carriage C carrying the rotatable platen P and longitudinally movably mounted on raceways at the rear of the fixed frame of the machine. The carriage is urged toward the left, as viewed from the front of the machine, by a spring in a drum 110 (Fig. 3) to which is secured one end of a tape 111, the other end of which is secured to the carriage. Normally, the carriage tabulates toward the left from one columnar position to the next near the end of each cycle of the machine under the control of a tabulating mechanism like that disclosed in the Rinsche Patents Nos. 1,516,685 and 1,580,534. The tabulating mechanism comprises a stop bar 112 (Fig. 19) rockably mounted on the carriage and carrying a plurality of column stops 113 adjustably positioned along the bar 112 in accordance with the columnar positions in which they are to hold the carriage by engagement with an abutment 114. A tabulating pawl 115 (Fig. 19) is pivoted on a slide 116 which moves downward during the forward stroke of each cycle, whereupon the pawl 115 is normally permitted to be rocked counterclockwise by its spring 117 to place its upper end under the active stop 113 so that when the slide 116 returns upward during the return stroke, the pawl 115 engages the active column stop 113 and rocks said stop and the bar 112 to disengage said stop from the abutment 114. The carriage immediately moves toward the left as viewed from the front or toward the right as viewed in Fig. 19, and thereby carries the said stop 113 away from the pawl 115 whereupon the bar 112 normally is immediately rocked back to its normal position by the usual spring 118 (Fig. 1) so that the stop 113 for the next column is in position to engage the abutment 114 and arrest the carriage in the next columnar position.

The carriage may be normalized, i. e., the tabulating mechanism may be disabled, by means of the usual "Carriage normal" key CN (Fig. 1) controlling means, such as disclosed in the Lundgren Patent No. 1,195,599 and including the slide 119, which disables the tabulating mechanism and enables the usual line spacing mechanism and so permits the carriage to remain stationary and causes the paper around the platen to be line-spaced after the operation of the printing mechanism in each machine cycle as long as said key remains depressed. Also, the lower motor bar L, when depressed to initiate a machine cycle, will disable the tabulating mechanism. A stud 120 (Fig. 1) secured in the lower motor bar stem 86 overlies the forward arm of a lever 121 pivoted on a fixed stud 122. The rear arm of lever 121 has a stud and slot connection with the forward arm of a lever 123 pivoted on a fixed stud 124. A lever 125 also pivoted on the stud 124 is straddled by a pair of studs 126 secured in the lever 123 to rock lever 125 with lever 123. The rear end of lever 125 overlies a roller on a stud 126 secured in the rear portion of a link 127 pivotally connected to the full stroke sector 49 so as to be pulled forwardly in the forward stroke of each machine cycle and returned rearwardly in the return stroke of the cycle. The stud 126 extends through a slot in a rocking cam 128 pivoted on a fixed stud 129. A spring (not

shown) normally holds the stud 126 upwardly in the rear end of the horizontal portion of the slot in the cam 128 so that the latter is not rocked during machine cycles. When the lower motor bar L is depressed, the lever 125 depresses the stud 126 into a pocket in the rear end of the slot in the cam 128 so that the latter is rocked clockwise in the forward stroke of each machine cycle initiated by depression of the lower motor bar, and the lower edge of cam 129 depresses a roller stud 119a carried by the slide 119 whereby the latter is depressed and enables the line-spacing mechanism and disables the carriage tabulating mechanism.

When the lower motor bar L, after being depressed, is manually held fully depressed until after a predetermined point in the return stroke of the resulting machine cycle, the carriage remains in the same columnar position for the next machine cycle and the paper around the platen is line-spaced. However, if manual pressure is withdrawn from the lower motor bar L before a predetermined point in the resulting machine cycle, and in any machine cycle initiated when the carriage is in the last columnar position at the end of its normal tabulating movement, except when such a machine cycle is initiated by depression and continued manual holding down of the lower motor bar, the carriage is returned across the machine to the right as viewed from the front or leftward in Fig. 19, after operation of the printing mechanism, by a motor-driven carriage return mechanism which, in the main, is similar to that disclosed in the Rinsche Patent No. 1,580,534.

As disclosed in detail in the Rinsche Patent No. 1,580,534, a rack bar 130 (Figs. 1, 13 and 19) on the carriage meshes with gear teeth on the periphery of the driven member 131 (Figs. 1 and 13) of a clutch located in a housing 132 and powered through a drive means in the housing 133 from the drive motor 25 of the machine. A lever 135 (Figs. 13 and 14), pivotally mounted at 136 on a stationary plate 137, causes engagement of the clutch when it is rocked clockwise in Fig. 13 (counterclockwise in Fig. 14) and disengages the clutch when said lever is returned to its normal position of Fig. 13. The clutch control lever 135, after being moved to either position, is yieldingly held in such position by a stud 138 on a pivoted spring-urged detent lever 139 engaging in one or the other of a pair of notches in said clutch control lever 135.

The rear arm of the lever 123 (Fig. 1) has two shoulders 140 and 141 between which is a forwardly extending slot wider than a stud 142 carried by a lever 143 (Figs. 1 and 6) pivoted on the stud 56 and urged clockwise by a spring 144 so that it tends to follow the lower arm of the three-armed lever 55 when the latter is rocked clockwise during the forward stroke of each machine cycle. When the lower motor bar L is in normal elevated position, the lower shoulder 140 is in the path of the stud 142 and when said motor bar is manually held fully depressed the upper shoulder 141 is in the path of the stud 142 and the lever 143 is thus rendered ineffective. But when manual pressure is withdrawn from the lower motor bar L immediately after it is depressed, the bell crank 39 and stud 91 permit the lower motor bar to return upward part of the distance to normal and sufficiently to align the slot between the shoulders 140 and 141 with the stud 142 so that the latter can enter the slot and the lever 143

can follow the three-armed lever 55 and permit a stud 145 in the lever 143 to act on the cam end of an arm 146 of a lever 147 and rock the latter counterclockwise about the stud 148 on which it is pivoted. The lower branch of the lever 147 has a stud and slot connection with an arm 149 secured on a shaft 150 journaled beneath the rear portion of the machine frame and also having secured thereon an arm 151 carrying a stud 152 positioned above a projection on a pawl 153 (Figs. 11 and 12) pivoted on a link 154 and held in contact with the stud 152 by a spring 155. A stud 156 projecting into a vertical slot in the link 154 is carried in the rear end of a lever 157 pivoted on a fixed stud 158 (Fig. 11) and urged clockwise (Fig. 11) by a spring 159. The forward cam end of the lever 157 is positioned in the path of a stud 160 on a crank arm secured on the shaft 40 so that the stud 156 is moved downward in each machine cycle near the end of the revolution of the shaft 40.

The pawl 153 is normally out of engagement with the stud 156 but when, during a machine cycle initiated by depression of the lower motor bar L and immediate withdrawal of manual pressure from said motor bar, the stud 142 enters the slot in the lever 123, the consequent rocking of levers 147 and arms 149 and 151 and depression of stud 152 rocks the pawl 153 to engage its hooked end under the stud 156 so that when the latter moves down during the machine cycle, the link 154 is also pulled down.

The upper end of the link 154 (Fig. 13) is connected to a slide 161 guided for vertical movement on a stud 162 secured in the plate 137. A pawl 163 pivoted on a stud 164 secured in the slide 161 is urged counterclockwise by a spring 165 to engage a lateral lug on its upper end against the edge of a latch pivoted on a stud 167 secured in the plate 137. When the link 154 and thus the slide 161 and pawl 163 are pulled down, the spring 165 positions the lateral lug on the end of the pawl 163 under a shoulder 168 on the latch 166. When the stud 160 passes the cam end of lever 157 and the stud 156 and link 154 are raised to normal by the springs 159 and 165, the latch 166 is rocked to disengage a shoulder 169 thereon from a lateral lug on a lever 170 pivoted on the stud 162, whereupon the lever is rocked clockwise by a spring 171 pulling upwardly on a lateral lug on a link 172 pivoted on a stud 173 which is secured in the lever 170 and passes through a slot in a lever 174 pivoted on a stud 175 secured in the plate 137. Thereby the link 172, which has a notch receiving a stud 176 on the lever 135 is elevated and rocks the lever 135 to engage the carriage return clutch. Also, a finger 177 on the lever 170 engages the lateral lug on the upper end of the pawl 163 and disengages it from the shoulder 168 to permit a later return of the parts to normal. A stud 178 on the lever 174 is raised into the path of a control roll 179 so adjustably located on the paper carriage that, when the latter has been returned a little beyond a selected columnar position (column 2 for the example of work to be described later), the roll 179 will depress the stud 178 and restore the lever 170 and link 172 to their normal depressed position where a spring 180 causes the latch 166 to relatch the lever 170 and the link 172, the lever 135 being rocked to clutch-releasing position by said link 172. Thereupon, the carriage moves a short distance in the tabulating direction until arrested by engagement of the abutment 114 with the column stop 113 for the selected columnar position.

A spring 181 (Fig. 14) yieldingly holds a stud 182 on the lever 185 in a slot in the end of a link 183 pivotally connected with one arm of a bell crank 184 controlling a switch 185 connected in parallel to the switch controlled by the link 34 to insure that the power circuit of the motor will be closed whenever the carriage return clutch is in engaged condition.

The stud 182 also overlies the end of a lever 190 pivoted on a stud 191 secured in a slide 192 slidably mounted on studs 167 and 193 secured in the plate 137. The lever is urged clockwise in Fig. 14 by a spring 194 but, with the slide 192 in its normal position of Fig. 13, a stud 195 secured in the plate 137 and engaged by an edge of the lever 190, holds the latter, as in Fig. 13, with its end depressed sufficiently to permit the lever 185 to occupy the clutch-releasing position.

A slide 196 is slidably mounted on studs 197 carried by the slide 192 and is urged to the right in Fig. 13, relative to the slide 192, by a spring 198 connected between one of the studs 197 and a stud 199 secured in the slide 196. The slide 196 also has an upturned ear 200 having a slot penetrated by a stud 201 secured in one arm of a bell crank 202 pivoted on a stud 203 carried in a downturned lug of the slide 192. When the carriage tabulates into its last columnar position, a control member 204 adjustably secured on the rack 130 engages the slide 196 and moves it slightly (leftward in Fig. 13) on and relative to the slide 192 against the yielding tension of the spring 198 thereby rocking the bell crank 202 to place a lug 205 thereon in the path of an arm of a bell crank 206 pivoted on the stud 175. At the same time, a stud 207 on the bell crank 202 cams the bell crank a short distance counterclockwise (Fig. 13) and lowers a link 208 pivotally connected to the second arm of the bell crank 206 and urged upwardly by a spring 209. A pawl 210 (Figs. 11 and 12) pivoted on the lower portion of the link 208 is urged counterclockwise in Fig. 11 by a spring 211 and has a forward projection underlying a stud 212 which is carried by the lever 185 and normally holds the hooked lower portion of the pawl 210 rearwardly of the path of the stud 156. However, the depression of the link 208 by the action of the control member 204 on the carriage as the latter moves in the tabulating direction into its final columnar position is sufficient to permit the pawl 210 to be rocked by its spring 211 to place its hooked lower end under the stud 156 so that when the stud 156 is lowered in a machine cycle, the link 208 is pulled further downward and through the bell crank 206, moves the slide 192 carrying the lever 190 leftward in Fig. 13 and to the right in Fig. 14 whereby a notch 213 in the edge of the lever 190 is brought into alignment with the stud 195 and permits the spring 194 to rock said lever 190 and the lever 185 to engage the carriage return clutch. At the same time, a finger on the slide 192 engages a stud 214 on the link 172 and disengages the latter from the stud 176 on the lever 185.

When the carriage has been returned a little past its first columnar position, a lug 215 (Fig. 19) on a control member 216 adjustably mounted on the rack 130 engages a lug 217 on the lever 190, rocking the latter back to normal position and then shifting the slide 192 back to normal position as a cam finger 218 on the control member 216 engages the stud 176 on lever 185 and returns the latter to clutch-releasing position, whereby the switch 185 is also reopened. The carriage is then permitted to move slightly in the tabulating

direction until stopped by engagement of a column stop 113 against the abutment 114 for the column 1 position of the carriage.

To facilitate the insertion and removal of the record material or work sheets about the platen P, the illustrated machine is provided with an automatically controlled power-operated front-feed mechanism like that disclosed in my prior Patents Nos. 2,202,595 and 2,202,596. Portions of this mechanism are shown in Figs. 1 and 18.

The illustrated machine has both manual and automatic controls for enabling it to perform various kinds of operations. The positioning of the crossfooter for engagement of the add pinions 99 or the subtract pinions 100 for engagement with the actuators is controlled manually through the subtract lever S (Fig. 3) and automatically by the carriage, as disclosed in the Pasinski Patents Nos. 1,778,506 and 1,911,768. The subtract lever S, pivoted on a fixed stud 220, has a rearward arm 221 connected to a link 222 having a stud 223 within a slot in a pitman 224. The rear portion of the pitman 224 has an upper branch having a shoulder 225 adapted to cooperate with a stud 226 and also has a lower branch having a shoulder 227 adapted to cooperate with a stud 228. The studs 226 and 228 are carried by a plate 229 secured upon the familiar 800 shaft which is rocked counterclockwise (Fig. 3) during the forward stroke and is returned clockwise during the return stroke of each cycle by the usual connections with the shaft 44. Normally, the parts occupy the + (adding and positive total-taking) position of Fig. 3. When, however, the lever S is moved to the - (subtracting and negative total-taking) position indicated in dot-and-dash line in Fig. 3, the link 222 and thus the rear end of the pitman 224 are raised to place the shoulder 225 in the path of the stud 226 so that, during the forward stroke of the cycle, the pitman will be drawn rearward. The forward end of the pitman 224 is pivotally connected to a cam lever 230 which is pivoted on the stud 220 and tumbles the crossfooter frame 101 in the well-known manner. When the pitman 224 is drawn rearward, the lever 230 is rocked clockwise from its Fig. 3 position to tumble the frame 101 to the - position where the subtract pinions 100 are presented for engagement with the actuators 98. When the lever S returns to the + position, the rear end of the pitman 224 is lowered again to place the shoulder 227 in the path of the stud 228 so that, during the forward stroke of the following cycle, the pitman 224 will be moved forward to rock the cam lever 230 counterclockwise to its Fig. 3 position to tumble the frame 101 to the + position to place the add pinions 99 in position for engagement with the actuators 98.

The subtract lever S also is pivotally connected to a link 231 having, near its rear end, a notch receiving a stud 232 on a lever 233 pivotally mounted on a fixed stud 234. A spring 235 connected to the lever 233 urges the parts to the + position of Fig. 3. A bell crank 236 pivotally supported on a rear arm of the lever 233 can be rocked against the tension of a spring 237 clockwise from its Fig. 3 position relative to the lever 233 but cannot be rocked counterclockwise beyond its Fig. 3 position relative to the lever 233. The rear arm of the bell crank 236 engages in the forked end of one arm 238 of a yoke pivotally supported on a fixed stud 239 and having a second arm 240 positioned to be acted upon by rolls 241 adjustably mounted on the carriage C. When 75 a carriage roll 241 moves over the arm 240 it de-

presses the latter and raises the arm 238 and bell crank 236. The lever 233, if not impeded, is thereby rocked clockwise (Fig. 3), the spring 237 being capable of overcoming the spring 235, and moves the link 231 and lever S forward to the - position so that, during the forward stroke of the next cycle, the crossfooter tumbling frame 103 will be tumbled to the - position. The spring 237 and bell crank 236 permit the lever S to be manually held in the + position even when there is a carriage roll 241 holding the arm 230 down.

The engagement and disengagement of the crossfooter pinions 99 or 100 and the actuators 98 are effected by mechanism which is like that shown in the Rinsche Patent No. 1,172,484 and the Pasinski Patents Nos. 1,778,506 and 1,911,768 and is normally conditioned for amount entering operations. The crossfooter main frame 103 pivoted at 104 has a rearwardly extending link 242 pivoted on its left-hand side member below the pivotal support 104. The link 242 has a shoulder adapted to cooperate with a stud 263 on the familiar arm 813 secured on the 300 shaft whereby the frame 103 will be rocked to engage the crossfooter pinions 99 or 100 with the actuators 98 at the end of each cycle of operation of the machine if they should be out of engagement with the actuators at that time. Above and below the pivotal support 104, the left side member of the crossfooter main frame 103 has two studs 244 and 245 adapted to cooperate with notched and shouldered upper and lower branches on the lower forward end of a link 246 pivotally connected at its upper rear end to the middle arm of the familiar three-armed rocking lever 913, the forward and rearward arms of which carry studs 247 and 248, respectively, which are adapted to cooperate with the usual pass-by pawl 821 carried by the arm 813. At the beginning of each cycle of operation, the pawl 821 engages the stud 247 and rocks the three-armed lever 913 counterclockwise in Fig. 3, thus moving the link 246 forward.

In amount entering operations, the forward end of the link 246 is held upward in the position of Fig. 3 by a spring 249 with the stud 244 engaged in the notch in the upper forward branch of said link 246. Thus, when the link 246 is moved forward at the beginning of the cycle, the crossfooter main frame 103 is rocked to disengage the crossfooter pinions from the actuators. Near the end of the forward stroke of the cycle, the pass-by pawl 821 engages the stud 248 but yields without rocking the lever 913. During the first part of the return stroke, however, the pawl 821 acts on the stud 248 to rock the lever 913 clockwise (Fig. 3) back to its normal position, thus drawing the link 246 rearward and rocking the crossfooter frame 103 to engage the crossfooter pinions 99 or 100 with the actuators 98, after which the latter are returned upward to normal from the differential positions corresponding to the depressed amount keys, whereby the amount which was set up on the keys is added or subtracted depending upon whether the pinions 99 or 100 are engaged with the actuators. At the end of the forward stroke, the pawl 821 engages the stud 247 but yields without rocking the lever 913.

The crossfooter may be "non-added." The pawl 821 acting on the stud 247 disengages the crossfooter pinions from the actuators at the beginning of the non-add cycle of the machine just as in an adding or a subtracting amount entering operation. However, when the pawl 821 approaches the stud 248 near the end of the for-

ward stroke of a non-add cycle, engagement of the pawl 821 with the stud 248 is prevented by a pawl 250 pivoted at 251 and normally held clockwise from its Fig. 3 position so that it normally does not interfere with the action of the pawl 821. The pawl 250 has a stud 252 engaged in the slotted end of a lever 253 which is connected through a link 254 with an arm 255 pivoted at 256 and held by a spring 256 in engagement with a lateral lug on a lever 257 also pivotally supported at 258. The rear end of the lever 257 engages in the slotted end of one arm 258 of a yoke 259 rockably supported on the stud 239 and having a second arm 260 adapted to be acted upon by rolls 261 adjustably mounted on the carriage C. When a carriage roll 261 holds down the arm 260 as shown in Fig. 3, the levers 257 and arm 255 are held in the clockwise position shown in Fig. 3, thus holding the link 254 and arm 255 down and the pawl 250 clockwise in the position shown in Fig. 3 to prevent the pawl 821 from acting on the stud 248. Thus, when the parts are positioned as shown in Fig. 3 by a roll 261 on the carriage, the crossfooter pinions will not be engaged with the actuators 98 at the beginning of the return stroke of the cycle.

The crossfooter main frame 103 also has pivotally connected thereto the forward end of a link 262, the rearward end of which is normally held elevated by a spring 263 and has a shoulder adapted to be engaged by a stud 264 on the arm 813 at the end of the forward stroke of the cycle. However, the arm 265 has a finger extending forward over a lateral lug on the forward end of the link 262 so that, when the arm 265 is moved to its Fig. 3 position by a carriage roll 261, the forward shoulder of the link 262 is held out of the path of the stud 264. The parts just described may also be moved to the non-add position illustrated in Fig. 3 manually by the usual "Non-add" key (not shown).

For total-taking operations, the connection between the link 246 and the crossfooter main frame 103 is altered. The bell crank 270 of the total key T carries a stud 271 which extends into a slot in a link 272, the lower end of which has a slot embracing a stud 273 on the forward end of the link 246 and is also connected to the upper end of the spring 249. Upon depression of the total key T, the link 272 is lowered, thereby lowering the forward end of the link 246 to disengage it from stud 244 and to permit engagement of the notch in the lower forward branch of said link 246 over the stud 245. Accordingly, when the link 246 is moved forward at the beginning of the forward stroke of the cycle, the crossfooter main frame 103 will be rocked to engage the pinions 99 or 100 with the actuator racks if they are not already so engaged. At the beginning of the return stroke, the rearward movement of the link 246 disengages the crossfooter pinions from the actuators and at the end of the return stroke the stud 248 engages the shoulder on the link 242 and re-engages the crossfooter pinions with the actuators.

In subtotal-taking operations, the crossfooter pinions are not disengaged from the actuator racks at the beginning of the return stroke of the cycle. The bell crank 275 of the subtotal key ST is connected to a link 276 having a shoulder 277 adapted to engage a stud 278 on the bell crank 270 of the total key T so that depression of the subtotal key ST also rocks the total key bell crank 270 and lowers the link 272 and the forward end of the link 246 as for total taking.

The link 276 carries a stud 279 which, upon depression of the subtotal key ST, engages an upwardly extending finger of the pawl 250 and rocks said pawl clockwise from its normal ineffective position to the position of Fig. 3, where said pawl prevents the pawl 821 from acting on stud 248 with the result that the link 246 is not moved rearward to disengage the crossfooter pinions from the actuators at the beginning of the return stroke of the cycle.

The mechanism may also be automatically conditioned for the taking of totals and subtotals from the crossfooter under the control of the carriage, as will be described later.

The illustrated machine is provided with an interlock means like that disclosed in the Pasinski Patent No. 1,778,506, which prevents depression of a total key whenever the position of the crossfooter tumbling frame 101 and the position of the subtract lever S do not both correspond to the sign of the total contained in the crossfooter.

Provided that the positions of the crossfooter tumbling frame and the subtract lever coincide and both correspond to the sign of the total contained in the crossfooter, totals and subtotals, both positive and negative, may be taken from said crossfooter without a spacing cycle prior to the total-taking cycle, the illustrated machine being provided for this purpose with mechanism like that disclosed in my Patent No. 1,844,070.

The total key bell crank 270 is connected through a link 290 to an arm 291 secured on a shaft 292 which extends through the machine. Near the right side of the machine, the shaft 292 has secured thereon an arm 293 (Fig. 6) connected to a link 294, the rear end of which is urged upward by a spring 295. The rear end of said link 294 has a shoulder 296 normally in front of a lateral lug on one arm of a latch lever 297 which is urged counterclockwise by a spring 298 and has a second arm having a shoulder 299 normally engaged behind a lateral lug on a lever 300 pivotally mounted at 301 and connected with the rear end of a link 302. As in my said prior Patent 1,844,070, rocking of the total key bell crank 270 a short distance toward total-taking position causes the shaft 292 to be rocked clockwise in Fig. 6 and the link 294 to move rearward and disengage the latch shoulder 299 from the lever 300. A spring 303 connected to the link 302 thereupon pulls said link rearward and rocks the lever 300 counterclockwise. A stud 304 on the lever 300 engages in a slot in the link 294 so that the rocking of lever 300 by the spring 303 completes the movement of the total key bell crank 270 to total-taking position.

The link 302 is connected at its forward end with the lower arm of a member 305 secured on a shaft 306. As in my said Patent No. 1,844,070, the counterclockwise rocking of said member 305 and shaft 306 by rearward movement of the link 302 results in the crossfooter being disengaged from the actuators, the restoring to normal of any actuators which are out of their normal "0" positions in consequence of tens transfers effected during the preceding cycle of operation, and the rocking of a bail 307 (Fig. 3) which releases the transfer pawl latches and permits any transfer pawls moved in tens-transfer operations during the preceding cycle to return to normal. The link 302 also carries a stud 310 (Fig. 6) which, when the link moves rearward, engages one arm of a bell crank 311, the other arm of which is connected through a stud and slot connection

312 to a spring 313 which, in turn, is secured to a connecting piece 314 (Fig. 1). The connecting piece 314 has an apertured lug through which the control link 34 passes and which is clamped between two nuts threaded on the lower end of the link 34 below the clutch arm 37 so that, when said connecting piece 314 is drawn upward, it not only rocks the arm 37 to cause engagement of the clutch and closing of the motor switch, but it also lifts the clutch control link 34 and thereby causes depression of the main motor bar M.

As the lever 300 is rocked counterclockwise (Fig. 6) by the spring 303, the stud 304 not only pulls the link 294 rearward but also depresses its rearward end and lowers the shoulder 296 below the lateral lug on the latch member 297 so as to permit the shoulder 299 on said latch member to re-engage behind the lateral lug on the lever 300 when it is restored to normal during the ensuing cycle. The restoring of the lever 300 during said cycle is effected by a stud 315 on the arm 46 engaging the lower arm of a lever 316 pivoted at 317 and having in its upper arm a slot in which engages a stud 318 on said lever 300.

Thus, the rocking of the total key bell crank 270 while it is free, i. e., while the position of the subtract lever S and the position of the crossfooter tumbling frame 51 correspond to the sign of the total in the crossfooter, not only effects the operations necessary to condition the machine for a total-taking or subtotal-taking cycle but also initiates the machine cycle for taking the total or subtotal.

If the position of the crossfooter tumbling frame and the position of the subtract lever S do not coincide with each other as well as correspond to the sign of the total in the crossfooter when the paper carriage occupies a columnar position where a total or a subtotal should be taken from the crossfooter, it will sometimes be necessary to give the machine a spacing cycle of operation for tumbling the crossfooter to the position corresponding to the sign of the total before the total key or subtotal key can be depressed. In such a case, the carriage should remain in the same columnar position until the total or subtotal is taken. With the illustrated machine set up for the example of work shown in Fig. 20 and presently to be described, it will

sometimes occur that a negative total is contained in the crossfooter when the carriage arrives in the column 5 position where a crossfooter subtotal is to be taken and printed, whereas the subtract lever S and the crossfooter would normally be in the + position at that time so the operator may be required to move the lever S to the - position and give the machine a spacing cycle to tumble the crossfooter to the - position. The machine is provided with a means like that

illustrated in Figs. 1, 10 and 11 of my prior Patent No. 2,202,596, which automatically disables the tabulating mechanism when the carriage reaches a predetermined columnar position, the column 5 position for the example of work shown in Fig. 20, and keeps it disabled until the total key or subtotal key is depressed so that the carriage will not tabulate to the next columnar position until the total or subtotal is taken. For the example of work illustrated in Fig. 20, the column stop 113 for the column 5 position of the carriage is slotted in the manner of the column stop 122 of my said Patent No. 2,202,596.

The machine is also provided with mechanisms as disclosed in my prior application Serial No. 75 177,435, filed December 1, 1937, but modified in

certain respects, for controlling skip tabulation of the paper carriage, automatic cycling of the machine under certain conditions when the carriage reaches a predetermined columnar position, and automatic carriage control of total taking. However, before proceeding further with the detailed description of the illustrated mechanisms, an example of work which the machine is adapted to perform will first be explained to facilitate understanding of the mechanisms described later.

Example of work

Fig. 20 illustrates a statement form such as prepared in a bank in connection with a customer's checking account. Columns 6 and 7 of the illustrated form are on a portion which can be detached from the remainder of the form along the line of perforations between columns 5 and 6. Columns 1, 2 and 3 are the usual old-balance-pickup and checks columns. Column 4 is the deposit and column 5 the balance column. Column 6 of the detachable portion is also a balance column and column 7 is the analysis column. Of course, any desired kind of analysis data could be entered in the analysis column 7, but, for the sake of an illustration, the figures which have been entered in column 7 of Fig. 20 represent the amounts of deposited checks which have been entered to the customer's credit but not immediately collected.

In making the entries in line I of the statement form of Fig. 20, the old balance of 100.00 is set up on the keyboard of the machine with the paper carriage in the column 1 position. The machine is set into operation by depression of the regular motor bar M, whereupon the old balance of 100.00 is added in the crossfooter. After the printing mechanism has operated to print 100.00, the carriage tabulates to the column 2 position where it automatically sets the crossfooter controls for subtraction. The operator sets up 25.00, the amount of a check, on the keyboard and again depresses the regular motor bar M, whereupon the machine operates to print the amount 25.00 in column 2 and subtracts this amount from the crossfooter. After the printing operation in column 2, the carriage tabulates to the column 3 position where the amount of another check 30.00, is entered and printed in column 3 and subtracted from the crossfooter in a cycle of operation also initiated by depression of the regular motor bar. The carriage then tabulates to the column 4 position where it automatically conditions the crossfooter controls for addition. The operator then sets up 75.00, the total of a number of deposit items, and depresses the regular motor bar M to give the machine a cycle of operation during which the amount 75.00 is added in the crossfooter and printed in column 4, whereupon the carriage tabulates to the column 5 position and the machine is automatically given a cycle of operation during which a subtotal is taken from the crossfooter and printed in column 5, leaving the total still in the crossfooter. The carriage then tabulates to the column 6 position, whereupon the machine is given another automatic cycle of operation during which the total is taken from the crossfooter, leaving the latter clear, and printed in column 6. Then the carriage tabulates to the column 7 position where the operator enters the amount 50.00 on the keyboard and depresses the regular motor bar to give the machine a cycle of operation during which the amount 50.00 is printed in column 7 and the

carriage return mechanism is set into operation to return the carriage to the column 1 position.

In making the next line of entries, line II on the form of Fig. 20, the operator reads the balance, 120.00, from column 5 or 6 in line I, sets this up on the keyboard and depresses the regular motor bar M to give the machine a cycle of operation for adding this amount in the crossfooter and printing it in column 1, after which the carriage tabulates to the column 2 position. Here the operator sets up 60.00, the amount of a check, on the keyboard and, noting that there is no further check to be posted, the operator depresses the upper motor bar U. Also noting that there is a deposit to be entered in column 4, the operator depresses said motor bar U and manually holds it fully depressed. In the ensuing operation of the machine, the amount of the check is subtracted from the crossfooter and printed in column 2, after which, because of the manual holding down of the upper motor bar, the carriage skip tabulates to column 4 and the machine comes to rest. Here the operator sets up the amount of 20.00 on the keyboard and, noting that this deposit does not require the entry of any analysis figures in column 7, the operator again depresses the upper motor bar U which causes a machine cycle in which the amount of the deposit is added in the crossfooter and printed in column 4, after which the carriage tabulates to column 5. When the carriage reaches the column 5 position, the machine is automatically cycled to take and print the crossfooter subtotal, after which the carriage tabulates to column 6, where the machine is automatically cycled to take the total from the crossfooter and print it.

As a result of the depression of the special motor bar for the column 4 entry in line II, the carriage return mechanism is set into operation after the printing of the total in column 6 and the carriage is returned to the column 1 position without entering the column 7 position. This saves the time which would ordinarily be required by tabulation of the carriage into the column 7 position and by manual depression of a motor bar by the operator after the carriage reaches the column 7 position.

It is also noted that the depression of the upper motor bar U which causes the carriage to be returned from the column 6 position instead of tabulating into the column 7 position is effected by the operator at the time of initiating the machine cycle for the entry in column 4. The presence or absence of analysis data to be entered in column 7 is determined by the nature of the item entry in column 4 and at the time of making the column 4 entry the operator has in mind the fact that analysis data are or are not to be entered in column 7. In line I, the operator, at the time of setting up the amount of the deposit, 75.00, on the keyboard for the entry in column 4, noted that some of the items included in the deposit required analysis data to be entered in column 7 and, therefore, depressed the regular motor bar M for the entry in column 4. The operator could utilize the time during which the machine was performing the two automatic cycles for printing the balance in columns 5 and 6 to determine the exact figures to be entered in column 7.

At the time of setting up the amount of 20.00 on the keyboard for entry in column 4 in line II, the operator, noting that no analysis data were to be entered in column 7 in line II, depressed the upper motor bar U and could then imme-

diately dismiss from mind any question regarding column 7. The operator did not have to wait until after the total was printed in column 6 to do anything further to cause the carriage return to column 1. Instead, the operator could utilize the time during which the machine was performing the automatic cycles for the printing of the balances in columns 5 and 6 in making ready for the next posting operation to be performed.

In line III, the old balance of 80.00 is entered in the pickup column 1 and 5.00, the amount of a check, is entered in column 2, both machine cycles being initiated by depressions of the regular motor bar M in the usual way. In entering 10.00, the amount of a second check, in column 3, the operator, noting that there is no deposit to be entered in column 4 in line III, depresses the upper motor bar U and immediately withdraws manual pressure from it. After the printing of the amount of 10.00 in column 3, the carriage tabulates to the column 4 position and the machine is immediately automatically given a cycle of operation during which the crossfooter is tumbled to adding position so that, when the carriage tabulates to the column 5 position, the add pinions of the crossfooter are positioned for engagement with the actuators for the automatic subtotal-taking operation during which the balance is printed in column 5. After the printing of the balance in column 5, the carriage tabulates to the column 6 position where the total is taken from the crossfooter and printed, after which the carriage is returned directly to the column 1 position without tabulating into the column 7 position. In the making of this third line of entries, the upper motor bar U was depressed while the carriage was in the column 3 position and remained depressed until near the end of the automatic cycle while the paper carriage was in the column 4 position. The upper motor bar U, being in depressed position during the cycle with the carriage in the column 4 position, caused the carriage return mechanism to be conditioned to return the carriage from the column 6 position to the column 1 position. This was correct because, there being no deposit to be entered in column 4, there would, in the example of work being described for the purpose of illustration, be no analysis data to be entered in column 7.

It should be noted at this point that the carriage is not necessarily returned to the column 1 position from the column 6 position at the end of a line of entries in which no entry is made in column 4. Suppose, for the sake of illustration, that the analysis data to be entered in column 7 might sometimes be based upon entries made in some other column besides column 4. For example, suppose that, in accordance with the system being used in a particular business, the nature of the debit item in column 2 or column 3 of line III was such as to necessitate the entry of data in column 7 even though there was no item to be entered in column 4. In that case, the operator, in initiating a machine cycle for the entry in column 3, would depress the upper motor bar U and maintain manual pressure on the motor bar until the machine comes to rest with the carriage in column 4. Then the machine would not perform an automatic cycle when the carriage reaches the column 4 position but the operator could then release the upper motor bar U and immediately depress the regular motor bar M to cause the needed cycle of operation in column 4 for tumbling the crossfooter to adding position, after which the balance would be printed

in columns 5 and 6 during automatic cycles of the machine and the paper carriage would tabulate into the column 7 position after the printing of the total in column 6.

5 In line IV on the work sheet shown in Fig. 20, there are no checks or debit items to be entered in columns 2 and 3. Noting this at the time of setting up the amount of the old balance, 65.00, on the keyboard for the column 1 entry, the operator depresses the upper motor bar U and continues to hold it fully depressed. After the printing of the amount of 65.00 in column 1, the carriage skip tabulates to the column 4 position. No automatic cycle is performed by the machine at this time because the upper motor bar is held fully depressed until the carriage reaches the column 4 position. The operator then releases the upper motor bar, sets up the amount of the deposit, 50.00, on the keyboard, and depresses the regular motor bar M to initiate the deposit entering cycle of the machine in view of the fact that the nature of some of the deposit items included in the 50.00 amount is such as to require the entry of analysis data in column 7.

10 The amounts entered in the several columns on the work form in Fig. 20 may be added into different ones of the multiple registers 105 or the multiple registers may be "non-added" in selected columns. Fig. 20 indicates that a roll 261^x is placed on the carriage to "non-add" the crossfooter when the carriage is in the column 7 position.

15 The foregoing description of one example of work is not to be considered as limiting the scope of the invention in any way. One example of work has been described merely to facilitate an understanding of the following detailed description of the mechanisms involved, and it will become clear from the following description of the mechanisms that the invention is equally well adapted for use in the performance of other varieties of work, many of which may involve different sequences of operations of the manual and automatic controls of the machine.

20 *Carriage skip tabulation*

25 The carriage tabulating mechanism which normally causes the carriage to tabulate to the next columnar position during the latter part of each machine cycle has already been briefly described. When there are no entries to be made in certain columns on the work form, as in column 2 in line II and in columns 2 and 3 of line IV of the work form shown in Fig. 20, it is desirable to have the carriage skip past these columns. This result is obtained under control by the upper motor bar U.

30 The stem 82 of the upper motor bar U is pivotally connected to an arm 325 (Fig. 1) pivoted on the stud 129 to guide said stem 82 in its movement. The stem 82 also carries a stud 326 normally positioned above the upper cam end of a lever 327 pivoted on the stud 128 and connected at its lower end to the forward end of a spring 328 which is connected at its rear end to the lever 147 and normally holds a stud 329 in the lever 147 in contact with the rear edge of the lower arm of the lever 327. The stud 329 also projects into a three-cornered cam slot 330 (Fig. 1) in a lever 331 pivoted on a stud 332 and having two forward projections, the upper of which is normally held engaged against the underside of a stud 333 by a spring 334 connected between said stud 333 and the lower forward projection of the lever 331.

The parts normally occupy the positions of Fig. 1, but when the upper motor bar U is depressed, the stud 326 cams lever 327 clockwise and the stud 333 depresses the forward end of lever 331 and the spring 328 pulls the lever 147 clockwise and positions the stud 329 in the forward corner of the slot 330. The stud 212 in lever 151 is thereby elevated sufficiently to permit the hook end of the pawl 210 to move into the path of the stud 156 so that when the latter descends during the machine cycle, it depresses the link 208. The downward movement of the link 208 causes a stud 336 therein (Fig. 13) to engage and depress a stud 337 in a slide 338 guided for vertical movement on studs secured in the plate 137. When depressed, the slide 338 is latched down, against the tension of a spring 339 urging it upwardly to its normal position, by a latch lever 340 which is pivoted on a stud 341 in the plate 137 and urged to latching position by a spring 341. The upper end of the slide 338 carries a roller stud 342 which, as shown in Figs. 11 and 19, is positioned under the cross member of a bail 343 which is pivoted on a shaft 344 supported in the side members of the frame of the carriage C and is urged counterclockwise in Fig. 11 by a spring 345. The right-hand side arm of the bail 343, as viewed from the front of the machine, has a downward extension 346 which, while the slide 338 and roller 342 are in their normal elevated positions, is positioned behind the rear end of an arm 347 secured on the column stop shaft 112. When the slide 338 and roller 342 are lowered and latched down in a machine cycle initiated by depression of the upper motor bar U, the bail 342 is rocked counterclockwise in Fig. 11 by the spring 345 and, when the column stop shaft 112 is rocked counterclockwise to tabulate the carriage during said cycle, the rear end of the arm 347 is depressed below the end of the extension 346 which then moves forwardly above the arm 347 to hold the column stops 113 clear of the abutment 114. The carriage, therefore, moves continuously in the tabulating direction until a stud 348 projecting rearwardly from a clip 349 adjustably secured in the desired position on the bail 343 acts on the upper end of the latch 340 and rocks the latter to release the slide 338, which is thereupon restored upwardly by its spring 339 and, through the roller 342, rocks the bail 343 to disengage the extension 346 from the arm 347, whereupon the column stop shaft 112 is rocked clockwise in Fig. 11 by the spring 118 (Fig. 1) to cause the carriage to be arrested by engagement of a stop 113 with the abutment 114. For the example of work shown in Fig. 20, the first skip release stud and clip 348 and 349 are secured on the bail 343 in position to trip the latch 340 when the carriage reaches a position where the column stops 113 for the column 3 and column 4 positions are on opposite sides of the abutment 114, whereby the carriage will always move to its column 4 position toward the end of a machine cycle initiated by depression of the upper motor bar U while the carriage is in any of its positions preceding the column 4 position.

It should be noted that the downward movement of the link 208 in a machine cycle initiated by depression of the upper motor bar U will not cause engagement of the carriage return clutch while the slide 196 and bell crank 202 are in their normal positions of Fig. 13.

In the example of work illustrated in Fig. 20, it is not desired that the carriage should skip

tabulate past the column 5 position from the column 4 position although, in some circumstances, as explained in connection with the illustrated example of work, the upper motor bar U is depressed for initiating the cycle of operation when the carriage is in the column 4 position. To prevent such an undesirable skipping of column 5, another skip-release member 348a, 349a is positioned on the bail 343 so as to release the skip latch 340 as the carriage moves out of the column 4 position and prior to the time it reaches the column 5 position so that the carriage can be arrested by the stop 113 for column 5.

15

Control of automatic machine cycles

The automatic cycling of the machine which occurs under certain circumstances when the carriage reaches the column 4 position in the example of work illustrated in Fig. 20, is controlled by the upper motor bar U in such a manner that, when the operator depresses the upper motor bar with the carriage in the first, second or third columnar position and immediately withdraws manual pressure from said motor bar, the machine is automatically given a cycle of operation when the carriage reaches the column 4 position, but when the operator depresses the upper motor bar U with the paper carriage in the first, second or third columnar position and continues to hold said motor bar fully depressed until the end of the forward stroke of the cycle, the machine is not given an automatic cycle of operation when the carriage reaches the column 4 position.

20 35 When the operator withdraws manual pressure from the upper motor bar U immediately after having depressed it, said motor bar is raised by its restoring spring 79 part way toward its normal undepressed position to an intermediate position before further upward movement is blocked by the crank 80 and stud 85 in cooperation with the repeat hook 38 and stud 39. The stem 82 of the upper motor bar U is formed with a cam finger 350 (Fig. 4) cooperating with a stud 351 carried by a member 352 pivotally supported on a shaft 353 and urged clockwise by a spring 354 (Fig. 6). The lower rearwardly extending end of the member 352 has a notch 355 (Fig. 4) located between rearward and forward shoulders 356 and 357 and cooperates with the stud 358 carried by the rearward arm of the three-armed lever 55 and in turn pivotally carries the two pass-by pawls 58 and 59. The cam finger 350 of the upper motor bar stem 82, the stud 351 and the member 352 are so arranged and dimensioned that, when the upper motor bar U is in its normal position, the lower cam edge of the finger 350 holds the member 352 in a position where the notch 355 is in the path of the stud 358. Thus, in a cycle of operation initiated, for example, by depressing the regular motor bar M, and while the upper motor bar U is in its normal upper position, the counterclockwise movement of the full-stroke sector 49 during the forward stroke of the cycle of operation will permit the three-armed lever 55 to be rocked clockwise by the springs 59 until the stud 358 reaches the bottom of the notch 355 in the member 352. This movement of the lever 55 is sufficient to carry the ends of both of the pass-by pawls 57 and 58 past the roller 60 with the result that, during the return stroke of the cycle of operation, the longer pawl 58 will act on the roller 60 to cam the arm 61 counterclockwise sufficiently far to release the repeat hook 38 from the stud

25 30 35 40 45 50 55 60 65 70 75

39 and permit the regular motor bar M to return to normal.

When the operator depresses the upper motor bar U and withdraws manual pressure from it to permit it to return to its intermediate position before the beginning of the return stroke of the cycle, the cam finger 350 and stud 351 permit the member 352 to occupy the position of Fig. 4 where the shoulder 356 is in the path of the stud 358. The shoulder 356 then limits the movement of the stud 358 during the forward stroke of the cycle as shown in Fig. 4, where the end of the shorter pass-by pawl 57 has passed the end of the roller 60 but the longer pawl 58 is prevented from passing the roller 60. During the return stroke of this cycle, only the shorter pawl 57 acts on the roller 60 with the result that the bail 61 is rocked counterclockwise only sufficiently to release depressed amount keys but not sufficiently to cause the projection 65 on the slide 64 to trip the repeat hook 38. Consequently, the regular motor bar M and also the upper motor bar U remain latched down at the end of this cycle.

The pawl 73 has a stud 360 cooperating with an upwardly extending finger 361 at the forward end of a repeat slide 362 slidably mounted on the stud 56 and having at its rear end a slot receiving a stud 363 on one arm 364 of a bell crank pivoted on a shaft 365. A second arm 366 of said bell crank has suitable connections, such as disclosed in my prior Patent No. 1,397,774, with an arm 367 (Fig. 19) of a yoke member 368 pivoted on a fixed stud 369 and having a second arm 370 which, in the present machine, carries a pass-by pawl 371 cooperating with repeat control rolls on the carriage to operate the slide 362. The arm 364 is urged to its normal position of Fig. 4 by a spring 372 (Fig. 6) connected to its upper end, which is also connected to one end of a spring 373, the other end of which (Fig. 4) is connected to the repeat slide 362 to urge it to keep the forward edge of the slot in its rear end engaged with the stud 363. When the stud 363 is engaged with the front edge of the slot in the slide 362, the spring 373 also urges the arm 364 counterclockwise because it is connected with said arm at a point appreciably above the stud 363.

It has already been explained that the carriage always tabulates to a predetermined columnar position, the column 4 position in the example of work illustrated in Fig. 20, as an incident to every machine cycle initiated by a depression of the upper motor bar U when the carriage is in a preceding columnar position, such as the column 1, 2 or 3 position in the example of Fig. 20. The carriage has a small repeat control roll 375 adjustably mounted thereon in such a position that, as the carriage reaches the above-mentioned predetermined columnar position (the column 4 position in the example of Fig. 20), said roll 375 engages the pawl 371 and depresses the arm 370 to move the repeat slide 362 rearward sufficiently to cause the finger 361 to engage the stud 360 and move the lower end of the pawl 73 rearward from above the stud 72. When the motor bars have remained latched as described above, and the link 34 is not otherwise impeded, the spring 35 will now raise the link 34 rapidly to initiate an automatic further cycle of operation of the machine. Thus, when the upper motor bar U is depressed while the carriage is in certain columnar positions and pressure is immediately withdrawn, the carriage will, as an incident to the cycle thus initiated, move to a predetermined columnar position and, thereupon, the machine

will automatically be given a further cycle of operation.

The slide 362 has a stud 376 (Fig. 5) engaged in the upper forked end of one arm 377 of a lever pivotally supported on the shaft 365 and having a second arm 378 engaging in front of a stud 379 on a rearward arm of the member 352. While the carriage is in the predetermined columnar position where the slide 362 is positioned by the small repeat roll 375, the column 4 position of Fig. 20, the lever 377-378 acting on the stud 379 holds the member 352 in a position such that the notch 355 is in the path of the stud 358. Consequently, both pawls 57 and 58 will pass below the roller 60 during the forward stroke of the machine cycle performed while the carriage is in the columnar position where the roll 375 is effective, and, during the return stroke of said cycle, the long pawl 58 will act on the roller 60 to operate the lever 61, slide 64 and repeat hook 38 to release the motor bars. Thus, the motor bars of the illustrated machine, set up for the example of work illustrated in Fig. 20, are always released at the end of the cycle performed while the carriage is in the column 4 position.

The upper motor bar U may be used to secure the same control of the carriage movement without causing an automatic cycle of the machine 30 following the cycle initiated by depression of said upper motor bar. When the upper motor bar U is depressed and manually held fully depressed, the upper rear cam surface of the finger 350 acts on the stud 351 to hold the member 352 35 is the same position which it occupies while the upper motor bar U is in its normally raised position, that is, with the notch 355 in the path of the stud 358. If the upper motor bar is held thus 40 fully depressed until the end of the forward stroke of the cycle, i. e., until the stud 358 has entered the notch 355, the repeat hook 38 is released during the return stroke of the cycle initiated by such a depression and manual holding 45 down of the upper motor bar U. It results from the foregoing that, if the operator withdraws pressure from the upper motor bar U after the stud 358 has entered the notch 355 and before the carriage roll 375 moves the repeat slide 362 rearward to move the pawl 73 away from the stud 50 72, the motor bars M and U will return to normal and the machine will stop at the end of the cycle thus manually initiated.

The machine is also provided with means which prevent an automatic cycle when the operator 55 holds the upper motor bar U fully depressed until the carriage roll 375 moves the pawl 73 rearward of the stud 72. A lever 380 pivoted on the shaft 353 and urged clockwise (Fig. 4) by a spring 381 (Fig. 1) has a cam 382 adapted to cooperate 60 with a cam 383 on the rear edge of the stem 82 of the upper motor bar U. A spring 385 connected at one end to the lower rear end of the lever 380 and at the other end to the upper arm of bell crank 386 pivoted on the stud 56 urges the said arm against a stud 384 on the lever 380. When the upper motor bar U is depressed below the previously described intermediate position the cams 383 and 382 cause the lever 380 to be rocked counterclockwise from its Fig. 4 position and the spring 385 rocks the bell crank 386 clockwise to press a lateral lug 387 on the lower arm of said bell crank against the rear edge of the motor control link 34. During the ensuing cycle, when the link 34 is lowered to its Fig. 4 position by the 65 70 75

stud 70 on the full-stroke sector 49, a shoulder 388 on the link 34 passes below the lug 387, which is then moved over said shoulder by the spring 385. As long as the upper motor bar U is thus held depressed below said intermediate position, the lug 387 prevents the link 34 from rising to initiate an automatic cycle. When the operator releases the upper motor bar, the repeat hook 38 having been released from the stud 39, both motor bars U and M will rise, the lever 380 will move clockwise and the stud 384 will rock the bell crank 386 to move the lug 387 rearward from the shoulder 388, but the stud 33 will then move downward to the lower end of the slot in the link 34 and an automatic cycle will not be initiated.

The motor control link 34 is also controlled as disclosed in my prior Patent No. 2,012,317 to prevent a cycle of machine operation from being initiated either manually or automatically while the carriage is not in any columnar position and, therefore, may be moving between columnar positions. As disclosed in my said prior Patent No. 2,012,317, when the active column stop 113 is moved by the tabulating pawl 115 or in any other manner out of engagement with the abutment 114, the latter moves to the left as viewed from the rear of the machine in Fig. 19. The next column stop 113 to cooperate with the abutment 114 to hold the carriage in a columnar position returns the abutment 114 in the opposite direction to its normal position, such movement being controlled by a dashpot (not shown) to cushion the arrest of the carriage. The abutment is also connected in the manner disclosed in my said patent to a bell crank 390 (Fig. 6) corresponding to the bell crank 101 of Fig. 13 of my said prior Patent No. 2,012,317 and having one arm overlying the rearward arm of a bell crank 361 pivoted at 392 and urged counterclockwise in Fig. 6 by a spring 393. The other arm of the bell crank 361 is connected through a link 394 to the lower end of a latch lever 395 pivoted intermediate its ends on a fixed pivot 396. The upper end of the lever 395 has a lateral lug 397 adapted to cooperate with a shoulder 398 on the rear edge of the link 34. When the active column stop 113 disengages from the abutment 114 and the latter moves to the left in Fig. 19, the spring 393 moves the lug 397 forward above the shoulder 398 and prevents the link 34 from rising to initiate a machine cycle. When another column stop 113 engages the abutment 114 and returns it to the right in Fig. 19 in cushioning the arrest of the carriage, the lug 397 is retracted rearward from the shoulder 398 to release the link 34 for upward movement if it is not otherwise impeded at that time.

With the carriage in a columnar position where the control roll 375 holds the repeat slide 382 sufficiently rearwardly to disable the pawl 70, the operator may sometimes give the machine a cycle of operation by depressing the lower motor bar L and maintain manual pressure thereon throughout the cycle to keep the carriage in the same position for a further entry. To prevent the machine from being cycled more than once while the operator holds the lower motor bar L down, a latch pawl 455 (Fig. 1) is pivoted on the stud 56 and urged clockwise by a spring 456. A lateral lug on the lower end of the pawl 455 is normally held rearwardly of the shoulder 388 on the link 34 by engagement of the pawl 455 against a stud 457 on the lever 125 which is lowered when the lower motor bar

L is depressed and permits the pawl 455 to engage against the edge of the link 34 so that when said link is lowered by the stud 70 during the machine cycle, the pawl 455 is pulled forwardly above the shoulder 388 to prevent a further machine cycle until the operator releases the lower motor bar L and thus permits the lever 125 to restore to its normal position and disengage the pawl 455 from the shoulder 388.

10   *Automatic total taking and subtotal taking*

The illustrated machine is provided with mechanism which, the machine being set up for the example of work illustrated in Fig. 20, causes 15 the machine, under certain conditions, to perform an automatic subtotal-taking operation when the carriage reaches the column 5 position and to perform an automatic total-taking operation when the carriage reaches the column 6 position. For convenience, this mechanism will 20 be referred to briefly as the automatic total mechanism.

A large repeat roll 400 is adjustably mounted 25 on the carriage so that, as the carriage comes to rest in the column 5 position, said roll 400 depresses the repeat lever 370 and moves the slide 362 rearward to such an extent that the upstanding finger 361 on the forward end of the slide 362 engages a lateral projection 401 (Fig. 8) on one side arm of a latch yoke 402 pivoted on the stationary stud 74 and urged clockwise to the position of Fig. 1 by a spring 403 (Fig. 8). The second arm of the latch yoke 30 has a hooked end 404 normally engaged under a lateral lug on the rear end of a lever 405 pivotally mounted on a stud 406 and urged clockwise by a spring 407. The large roll 400 depresses the repeat lever 370 and moves the slide 362 rearward to such an extent that the finger 361 engages the lateral lug 401 on the latch yoke 402 and moves the latter counterclockwise to withdraw the hook 404 from beneath the lateral lug on the lever 405 which is thereupon moved clockwise about its pivot 406 by its spring 407 and strikes a lateral lug on the rear end of a latch lever 410 also pivoted on the stud 406 and urged counterclockwise by a spring 408. The latch lever 410 has a shoulder 411 on its forward arm normally engaged behind a lateral lug on one 45 arm 412 of a lever 413 pivotally mounted on the shaft 292. The lever 405 rocks the latch lever 410 clockwise, raising its shoulder 411 above the lug on the arm 412 whereupon the lever 413 is rocked clockwise by a strong spring 415 (Fig. 6) connected at one end to the lower arm of the lever 413 and at its other end to the lower arm of a lever 416 pivotally mounted on a fixed stud 417 and having an upper arm having a lateral lug 418 normally engaged behind the hooked end 419 of one arm of a latch lever 420 pivoted at 421 and urged counterclockwise by a spring 422. The spring 415 is limited by a telescoping sleeve 431 and rod 432 located within the spring 415 and connected to the levers 413 and 416, respectively.

When the lever 413 is rocked clockwise by the spring 415, an arm 423 of said lever 413 engages a stud 424 secured on the usual T-shaped arm 425 which is secured to the shaft 292. Thus, 70 when the paper carriage moves to a position where a large roll 400 depresses the repeat lever 370, the lever 413 will be rocked clockwise, except when prevented by means hereinafter described, and will rock the T arm 425 and shaft 292 clockwise in Figs. 6, 8 and 9. The connection of the

shaft 292 with the total key bell crank 270 and the manner in which the rocking of the shaft 292 clockwise in Fig. 6 releases the lever 300 from the latch 299 to permit the spring 303 to condition the machine for total taking and to cause the motor to give the machine the cycle of operation for taking the total have been described previously.

As already mentioned, the spring 303 depresses the regular motor bar M after the total key T is depressed and the motor bar M is then latched in depressed position by the repeat hook 38 engaging under the stud 39 on the lever 27. The lever 27, near its forward end, has a stud 426 which, when the regular motor bar M is depressed after depression of the total key T, moves down in front of the head of the T arm 425 and prevents the total key bell crank 270 from returning to normal prior to the release and return to normal of the regular motor bar M.

A non-add roll 261 is so positioned on the carriage as to depress the non-add arm 260 (Fig. 3) when the carriage is in the column 5 position where the large roll 400 depresses the repeat lever 370. In the manner already explained, this depression of the non-add lever 260 by the non-add roll 261 moves the non-add pawl 250 to the active position of Fig. 3 where it prevents the pass-by pawl 821 from acting on the stud 248 of the lever 913 at the beginning of the return stroke of the cycle of operation. Consequently, the crossfooter pinions are not disengaged from the actuators 98 at that time but remain engaged with the actuators during the return of the latter to normal so that the two rolls 400 and 261 together automatically cause a subtotal to be taken from the crossfooter in the same manner as though the subtotal key ST were depressed.

The large roll 400, which is active in the column 5 position of the carriage, is so positioned that it holds the slide 362 in such a position as to cause a further automatic cycle of operation of the machine when the paper carriage tabulates to the column 6 position. The position of said roll 400 is such that, while the paper carriage is at rest in the column 5 position, said roll 400 is above the highest portion of the pass-by pawl 371 (Fig. 19) carried by the repeat lever 370 and causes the repeat slide 362 through the lever 377-378 to hold the member 352 sufficiently counterclockwise from its Fig. 4 position to place the shoulder 357 in the path of the stud 358. This, as shown in Fig. 7, so limits the clockwise movement of the lever 55 during the forward stroke of the cycle that the pass-by pawls 51 and 58 do not pass below the roller 60 during the forward stroke and the repeat hook 38 is not released from the stud 39 during the return stroke of the cycle. Consequently, the motor bar M remains depressed at the end of the cycle and the total key T cannot restore to normal in the usual manner because the stud 426 is in front of the head of the T arm 425.

As the carriage tabulates toward the column 6 position near the end of the automatic subtotal-taking cycle initiated when the carriage was in the column 5 position, another repeat roll 430 passes over and beyond the apex of the pass-by pawl 371 on the repeat lever 370 and momentarily moves the repeat slide 362 sufficiently rearward to move the lower end of the pawl 73 rearward of the stud 72 so that the motor control link 34 is permitted to rise and cause the motor to give the machine a further automatic cycle of operation when the carriage arrives in the

column 6 position. The total key T is still latched down and, as there is no non-add roll 261 acting on the non-add arm 260 when the carriage is in the column 6 position, the automatic operation of the machine initiated when the carriage reaches the column 6 position will be a total-taking operation at the end of which the crossfooter is left clear.

As the carriage roll 430, when the carriage has come to rest in the column 6 position, does not hold the slide 362 and the two-armed lever 377-378 sufficiently rearward to hold the shoulder 357 in the path of the stud 358 but permits the member 352 to be positioned by engagement of the stud 351 against the finger 350 on the stem of the upper motor bar U which is in its normal raised position, the notch 355 of the member 352 is under the stud 358 and permits both pass-by pawls 51 and 58 to move their ends below the roller 60 during the forward stroke of the automatic total-taking cycle with the carriage in the column 6 position, with the result that, during the return stroke of said cycle, the repeat hook 38 is unlatched from stud 39, which permits the motor bar M to return to normal and remove the stud 426 from in front of the head of the T arm 425 to permit the latter and the total key bell crank 270 to be returned to normal toward the end of said cycle by the usual spring 428 (Fig. 6) connected to an arm 429 secured to the shaft 292.

The automatic total mechanism is restored to normal in the following manner:

A lever 435 pivoted on a fixed stud 436 is urged counterclockwise in Fig. 6 by a spring 437 to engage the lower arm 438 of said lever against the stud 70 on the full stroke sector 49. Near the end of the forward stroke of each machine cycle, the stud 70 acts on a cam portion 439 on the lower end of the arm 438 to rock the lever 435 clockwise. A pawl 440 pivotally mounted on the forward upper arm 441 of the lever 435 (Figs. 6 and 9) has a hook portion 442 and a shoulder 443 (Fig. 9). The pawl 440 is urged clockwise by a spring 444. When the lever 435 is moved clockwise by the roller stud 70, the pawl 440 is moved rearward, but, as long as the T arm 425 is in its forward normal position, the stud 424 engages the top of the hooked end 442 of the pawl 440 as in Fig. 9 and holds it down so that the shoulder 443 will not engage a stud 445 on the upper arm of the latch lever 420. But, when the T arm 425 moves to the total-taking position of Fig. 6, the stud 424 moves away from the end 442 of the pawl 440 and permits the shoulder 443 to engage behind the stud 445 so that, when the lever 435 is rocked clockwise near the end of the forward stroke of the subtotal and total-taking cycles during which the T arm 425 is in the total-taking position of Fig. 6, the pawl 440 rocks the latch 420 clockwise against the action of its spring 422 and thus unlatches the lever 416.

After the power spring 415 has acted to pull the total-taking control means to total-taking position, its tension has been largely relieved and, when the latch 420 has been released, a relatively light spring 446 (Figs. 6 and 9) suffices to swing the levers 413 and 416 counterclockwise, causing the lever 416 to follow the stud 70 during the return stroke of the cycle. The spring 446 thus returns the lever 413 to its normal position of Figs. 1 and 8.

The lever 413 is not relatched by the shoulder 411 on the latch lever 410 at the end of the

subtotal-taking cycle initiated by the carriage roll 400 because said latch lever 410 is not in its normal position of Fig. 8. Near the end of the forward stroke of this cycle, the roller stud 70 cams the lever 435 clockwise and a rearward projection on the arm 441 thereof engages a downwardly extending finger 447 of the lever 405 and rocks the latter counterclockwise to raise the lateral lug on the end of said lever above the hook 404 of the latch bail 402, but the latter is held out of latching position by the carriage roll 400 acting through the slide 362. Consequently, early in the return stroke of this cycle, the spring 407 returns the lever 405 to the position of Fig. 9 where it holds the latch lever 410 out of latching position.

During the forward stroke of the total-taking cycle initiated by the roll 430 with the carriage in the column 6 position, the stud 70 returns the levers 416 and 413 to the position of Fig. 6. The lever 416 is not now relatched in its normal position of Figs. 6 and 9 because the latch 420 is again moved out of latching position by the pawl 440, but the lever 435 and the lever 405 are again rocked counterclockwise to raise the lateral lug on the end of the lever 405 above the hook 404 at this time. As the carriage roll 430 does not hold the latch 402 out of latching position, the lever 405 is relatched in normal position so that, when the spring 446 again moves the lever 413 to its Fig. 9 position and the lever 416 to the dot-dash-line position of Fig. 6 during the return stroke of the total-taking cycle, the shoulder 411 on the latch lever 410 can move behind the lug on the arm 412 of lever 413 and relatch the latter in normal position. Near the end of this cycle, the motor bar M returns to normal and the T arm 425 returns forward to normal position where the stud 424 again depresses the pawl 440 to remove its shoulder 443 from in front of the stud 445 so that the latch 420 is permitted to relatch the lever 416 when the latter is again returned to normal position and the spring 415 is retensioned by the stud 70 during the forward stroke of the next machine cycle, that is, the cycle following the total-taking cycle.

If the light spring 446 should fail to rock the lever 413 quite far enough counterclockwise (Fig. 9) during the return stroke of the total-taking cycle to permit it to be relatched by the latch lever 410, the lever 416 will still be relatched in normal position during the following cycle. In that case, the lever 413 would, nevertheless, be in about its Fig. 9 position at the beginning of said following cycle and depression of the regular motor bar M to initiate said following cycle would move the stud 426 down behind the T-head of the lever 425 to hold the latter and the lever 413 in their Fig. 9 positions. Consequently, the shoulder 443 on the pawl 440 will be prevented from engaging the stud 445 on the latch 420. Thus, the latch 420 will be free to relatch the lever 416 during the cycle following the total-taking cycle. Also, near the end of the forward stroke of said following cycle, a bell crank 450 (Fig. 6) pivoted on a fixed stud 451 and having in its downward arm a slot receiving a stud on the upper end of the arm 441 of the lever 435 will be rocked counterclockwise by said lever 435 so that a cam head 452 on the end of the forward arm of said bell crank 450 will act on a stud 453 on the end of the arm 423 of the lever 413 and positively cam the latter far enough counterclockwise to permit the shoulder 411 on the latch lever 410 to drop be-

hind the lateral lug on the arm 412 of said lever 413.

As already mentioned, it may occur that, in the illustrated machine set up for the example of work shown in Fig. 20, the crossfooter 99-103 contains a negative total or overdraft balance when the carriage reaches the column 5 position and the carriage roll 400 causes the latch 401-404 to be moved to release the lever 405 of the automatic total mechanism. Also, as previously mentioned, the subtract lever S and the crossfooter tumbling frame 101 are normally in the + positions when the carriage tabulates into the column 5 position at the end of the machine cycle initiated with the carriage in the column 4 position. (An exception to usual conditions will be referred to later.) In the above-mentioned circumstances, the previously mentioned total key-subtract lever-crossfooter interlock would prevent movement of the total key bell crank 270 to total-taking position. The illustrated machine is provided with means somewhat different than the means disclosed in my previously mentioned application Serial No. 177,435 for preventing release of the automatic total mechanism by the carriage roll 400 when the position of the crossfooter tumbling frame 101 does not correspond to the sign of the total in the crossfooter. This means is controlled by a portion of the above-mentioned interlock means which includes a three-armed lever 460 (Figs. 3, 6, 8 and 9) corresponding to the levers numbered 300, 303, 307 in the previously mentioned Pasinski Patent 1,778,506.

As disclosed in said Pasinski patent, the three-armed lever 460 is controlled from the highest order pinions of the crossfooter and occupies the position shown in Fig. 6 at all times while the total in the crossfooter is positive, but is positioned clockwise of the Fig. 6 position with the pointed end of its lower arm forward of the detent stud 461 as in Figs. 8 and 9 while a negative total is present in the crossfooter. A stud 462 on the upper arm of the lever 460 engages in a slot with upturned ends in a link 463. The forward end of the link 463 is urged downward by a spring 464 and said link is movable forwardly and rearwardly under control of the lever 239 (Fig. 3), the position of which always corresponds to the position of the crossfooter tumbling frame 101. The arrangement is such, as disclosed in said Pasinski patent, that whenever the position of the crossfooter tumbling frame corresponds to the sign of the total in the crossfooter, the stud 462 is in one or the other of the upturned ends of the slot in the link 463, the forward end of which, therefore, occupies a position at the same height as in Figs. 1, 6 and 9, but whenever the position of the crossfooter tumbling frame does not correspond to the sign of the total in the crossfooter the stud 462 is positioned in the low mid-portion of the slot so that the forward end of the link occupies a higher position as in Fig. 8, which shows the positions of the parts when the crossfooter tumbling frame is in its + position and the crossfooter contains a negative total.

A bail 470 extending across the upper front portion of the machine (Figs. 3, 6, 8 and 9) and pivotally mounted on the rod 471 is urged clockwise (Figs. 6, 8 and 9) in a manner which will be explained later, and has an arm 472 carrying a stud 473 engaging against the top edge of the forward portion of the link 463. At the left-hand side of the machine the bail 470 has an arm 475 (Fig. 3) having a yieldable connection 476 with a for-

ward branch of a lever 477 which is pivoted at 478 and urged clockwise by a spring 479 which thus also urges the bail 470 counterclockwise in Fig. 3 and clockwise in Figs. 6, 8 and 9. At the right-hand side of the machine, the bail 470 has an arm 480 on the downward and rearward end of which is a lateral lug 481 adapted to cooperate with the end of the forward arm 482 of a latch lever fixed on the shaft 30 and having a downwardly and rearwardly extending arm 483 with a hooked end adapted to cooperate with a squared stud 484 on the lever 405. The latch lever 482—483 is urged counterclockwise by a spring 486 (Fig. 8) connected to an arm 487 also fixed on the shaft 30.

When the position of the crossfooter tumbling frame 101 corresponds to the sign of the total in the crossfooter and the forward end of the link 463 occupies a lower position as in Fig. 6 or 9, the bail 470 and arm 480 occupy the position shown in Figs. 6 and 9, and the lever 477 occupies the position of Fig. 3, where its upper end is forwardly of a stud 474 on the total key bell crank 270 and does not interfere with depression of the total key. During each cycle of operation of the machine, when the lever 435 is rocked clockwise by the stud 70, it rocks the lever 405 counterclockwise to raise the rear end of the latter above the position of Fig. 1, i. e., substantially above the hook 404 of the latch yoke 402. In this movement of lever 405, a stud 485 (Figs. 6, 8 and 9) on said lever acts on the rear cam edge of the arm 483 and rocks the latch lever 482—483 clockwise to lift the forward end of the arm 482 above the lateral lug 481 on the arm 480 and to place the hooked end of the arm 483 under the squared stud 484.

It will be remembered that the tumbling of the crossfooter, when it is effected, occurs during the forward stroke of the machine cycle. If such tumbling of the crossfooter occurs in a cycle of machine operation initiated when the carriage occupies the columnar position ahead of a total-taking or subtotal-taking columnar position and tumbles the crossfooter to a position not corresponding to the sign of the total in the register at that time, the front end of the link 463 will be elevated at the time the crossfooter is tumbled and the bail 470 will be rocked to place the lateral lug 481 on the arm 480 beneath the end of arm 482 so that the hooked end of the arm 483 is prevented from moving out from under the stud 484. The bail 470 will also move the upper end of the lever 477 under the stud 474 on the total key bell crank 270 to block depression of the total key. If the amount entered into the crossfooter during the return stroke of the cycle does not change the sign of the total to bring it into agreement with the position of the crossfooter tumbling frame 101, the lug 481 on arm 480 will remain under the end of arm 482 and the lever 405, when released from the latch 404 by the roll 400 as the carriage moves into the balance column, will not be permitted to move far enough to trip the latch 410 and release the arm 412.

Thus, if the sign of the total in the crossfooter and the position of the crossfooter tumbling frame 101 do not correspond when the carriage arrives in the balance column, the machine will not automatically perform a subtotal-taking or total-taking cycle. Moreover, the total key and subtotal key will be locked. If, however, the amount entered in the crossfooter during the return stroke of the cycle in which the crossfooter is tumbled, with the carriage in the columnar po-

sition preceding the balance columnar position, should change the sign of the total in the crossfooter to bring it into agreement with the tumbled position of the crossfooter, the bail 470 will be moved to move the upper end of the lever 477 forward from under the stud 474 and the lateral lug 481 on the arm 480 forward from under the end of the arm 482, which permits the latch lever 482—483 to move counterclockwise to withdraw the hooked end of the arm 483 from under the stud 484 so that, as the carriage reaches the balance columnar position and the roll 400 on the carriage operates the latch 404, the lever 405 will be free to trip the latch 410 and release the automatic total mechanism to give the machine an automatic total-taking or subtotal-taking cycle of operation.

With the illustrated machine set up for the example of work illustrated in Fig. 20, it will usually happen that the tumbling of the crossfooter, during the forward stroke of the cycle of operation of the machine when the carriage is in column 4 or "deposit" columnar position which immediately precedes column 5 or first "balance" columnar position, will position the crossfooter tumbling frame 101 in correspondence with the sign of the total in the crossfooter so that, at the end of the forward stroke of said cycle when the forward end of arm 482 is elevated, the lug 481 on the arm 480 will be forward of the end of arm 482 and the latch lever 482—483 may return to releasing position with the forward end of arm 482 behind the lateral lug 481 on the arm 480 during the return stroke of said cycle. Then, the lever 405 will be free of the latch arm 483 when the carriage tabulates into the "balance" columnar position.

No misoperation can result from the fact that the end of the arm 482 is behind the lug 481 on the arm 480 during the return stroke of the cycle initiated with the carriage in the columnar position preceding the "balance" columnar position, because any amount entered in the crossfooter during the return stroke of a cycle, in the forward stroke of which the crossfooter is tumbled into a position in agreement with the sign of the total in the crossfooter, will also always be of the same sign of the total and cannot change the sign of the total and, therefore, can never require that the lug 481 on the arm 480 should move rearward to a latching position under the end of arm 482.

Thus, it will be seen that the bail 470, arm 480, and latch lever 482—483 will always prevent operation of the automatic total mechanism under the control of the carriage when the carriage reaches the "balance" columnar position at any time when the position of the crossfooter tumbling frame 101 does not agree with the sign of the balance in the crossfooter.

If the machine does not automatically perform a subtotal-taking or total-taking cycle when the carriage reaches the "balance" columnar position, the operator may proceed with the work in a number of ways, depending upon the practice of the office or bank and the nature of the work to be performed. In the work illustrated in Fig. 20, consisting of the posting of bank customers' checking accounts, the failure of the machine to perform a balance printing cycle when the carriage arrived in the "balance" column would be due to the presence of a negative total or overdrawn balance in the crossfooter, provided that the operator did not manually interfere with the automatic control of the subtotal tract lever S at the time of initiating a machine

cycle with the carriage in the "deposit" columnar position immediately preceding the first "balance" columnar position. Also, it would usually be undesirable to print an overdraft balance on the customer's statement form. In such circumstances, it is possible for the operator manually to return the carriage to one of the preceding columns such as "deposit" columns, set up on the keys the amount of the check which caused the overdraft, hold the subtract lever in the adding position manually, if required, and give the machine a cycle of operation during which the amount of the check would be added in the crossfooter so that the total in the crossfooter would again become positive. During this cycle, the lever 405 will be relatched by the latch 402, 404 before the lug 481 moves forward from under the end of the arm 482, but at the end of the cycle the carriage will again tabulate into the "balance" columnar position where the roll 400 will trip the latch to cause an automatic cycle of operation of the machine during which the balance will be printed.

In some classes of work, however, the object in preventing an automatic balance printing cycle of operation of the machine when the carriage tabulates into the balance columnar position might be merely to give the operator warning of the presence of a balance of a sign opposite to that normally present when the carriage reaches such position and to forcibly impress such warning on the mind of the operator by requiring the operator to perform special acts whenever a balance of such nature is encountered. In such a case, the operator may proceed to cause the balance to be printed in the balance column. The most simple procedure requires the operator to move the subtract lever S to the position corresponding to the sign of the total in the crossfooter and hold it there while manually depressing the regular motor bar M to give the machine a spacing cycle. Fig. 8 illustrates the position of the parts as the carriage arrives in the first balance columnar position with a negative total in the crossfooter with the machine set up for the work illustrated in Fig. 20. After shifting the subtract lever S to its — position, depression of the motor bar M will give the machine a spacing cycle during which the crossfooter tumbling frame 101 will be tumbled to the position corresponding to the sign of the total and the bail 470 will be rocked to withdraw the lug 481 from under the end of the arm 482. The lever 405 will now be free from both the latch 483 and 404, but a balance-printing cycle will not automatically follow the spacing cycle because the roll 400 on the carriage has caused the motor bar to remain latched down at the end of this spacing cycle with the carriage in the "balance" columnar position, and the stud 426 remains down behind the T-head of the lever 425, thus preventing clockwise rocking of the shaft 292.

During the above-described spacing cycle, the carriage does not tabulate but remains in the same columnar position because the tabulating mechanism, as previously explained, is disabled by the slotted column stop 113 for the "balance" columnar position and remains disabled until the total key bell crank 270 is moved to total-taking position. Thus, the carriage roll 400 continues to hold the repeat arm 370 down and causes the repeat slide 362 to continue to hold the pawl 73 rearward of the stud 72 on the motor control link 34. Though the motor bar M remains latched down and the motor control link

34 is held down by neither the pawl 73 nor the latch 395 controlled by the abutment 114, still an automatic cycle of the machine does not follow the above-described spacing cycle. Because the carriage remains stationary in the same columnar position, the latch 395 is held in the ineffective position of Fig. 6, and as the pawl 73 is held rearward of the stud 72 throughout the spacing cycle while the motor bar M remains latched down, the spring 35 will maintain the projection 71 of the motor control link 34 in contact with the stud 70 throughout most of the return stroke of the spacing cycle. However, the repeat hook 38 and the slot in the upper end of the link 34 are so proportioned that, when the motor bar M is latched down by the repeat hook 38 without manual pressure on said motor bar, and link 34 is pulled upward relatively slowly during the return stroke of a cycle as the projection 71 follows the stud 70, the stud 33 on the lever 27 does not permit the link 34 to move upward quite far enough to engage the clutch and close the motor switch. Instead, the link 34 stops slightly before the full-stroke sector returns to normal position so that, at the end of the spacing cycle, there is a slight clearance between the projection 71 and the stud 70. One-sixteenth of an inch is sufficient. The regular motor bar M can be manually depressed slightly below the position in which it is latched by the repeat hook 38 and, when manually depressed, it, therefore, pulls the motor control link 34 upward to bring the projection 71 into contact with the stud 70. This slight additional upward movement of the link 34 is sufficient to engage the clutch and close the motor switch. This arrangement does not prevent the machine being given an automatic cycle when the paper carriage tabulates to a new columnar position as, for example, when the carriage tabulates into the column 4 position when set up for the example of work illustrated in Fig. 20. While the carriage is tabulating, the lug 397 on the latch 395 moves over the shoulder 398 on the link 34 and prevents the projection 71 from following the stud 70 during the return stroke of the cycle in which the carriage tabulates. Also, the pawl 73 normally moves over the stud 72 when the link 34 is depressed by the stud 70 and the pawl 73 remains over the stud 72 until either the motor bar M returns to normal or the repeat slide 362 moves the pawl 73 rearward. When the carriage tabulates into a columnar position where an automatic cycle is desired, a repeat roll on the carriage moves the slide 362 rearward and thus removes the pawl 73 rearward from above the stud 72. The retraction of the latch 395 and of the pawl 73 under such circumstances occurs after the stud 70 has returned to normal so that, if the motor bar M is latched down at that time, the spring 35 will move the link 34 upward very rapidly whereby said link 34 and the parts operated thereby acquire a momentum which, when the lower end of the slot in the link 34 contacts the stud 33, rocks the levers 27 and 28 counterclockwise and clockwise, respectively, in Fig. 6 against the tension of the spring 32, and causes the link 34 to move upward until the projection 71 is stopped by the stud 70, after which the link 34 is returned downward a slight distance again by the spring 32. However, the extra upward movement of the link 34 caused by its momentum engages the clutch and closes the motor switch. As already mentioned, however, the latch 395 and pawl 73 are inactive during the

spacing cycle while the carriage remains stationary in the balance column and the link 34 returns upward relatively slowly without gaining sufficient momentum to move it upward beyond the position determined by the repeat hook 38 and the automatic cycle does not follow the spacing cycle. To further insure the prevention of an automatic cycle following the spacing cycle, a spring 489 (Fig. 10) is connected to the rear end of the lever 21 to urge said lever clockwise and aid the spring 32 in checking the upward movement of the link 34 when the projection 71 follows the stud 70 during the return stroke of the spacing cycle.

With the parts in the positions of Fig. 8 before the spacing cycle, they will move during the spacing cycle to the positions of Fig. 9. As shown in Fig. 9, the illustrated machine has a key 490 on a crank 491 which is pivoted on shaft 29 and has a stud 493 engaging a lever 494 which is pivoted at 495. Depression of the key 490 causes the stud 493 to rock the lever 494 counterclockwise so that a projection 496 on said lever engages another lug 497 on the slide 64 and moves said slide forward against the tension of spring 84a whereby its lug 65 operates the repeat hook 38 to permit the motor bar M to return to normal. Immediately the stud 426 has cleared the T-head of the arm 425, the latter and the shaft 292 can be rocked by the spring 415 to cause an automatic cycle during which the true balance in the crossfooter will be printed.

After the carriage arrives in the "balance" columnar position with the sign of the total in the crossfooter not in agreement with the position of the crossfooter tumbling frame, and with the automatic total mechanism locked, it is also possible for the operator to proceed in another manner.

The illustrated machine is provided with a key usually referred to as a "Cycle normal" key or a "Repeat normal" key, designated RN in Figs. 1, 4 and 5. The stem 500 of said key is pivoted on a cam lever 501 (Fig. 5) which is rockably supported on the shaft 365. If the key RN is moved rearward after it is depressed, the lower edge of a notch 502 in the stem can be moved under the edge of the top plate of the keyboard in the usual manner to latch the key in depressed position for any desired length of time, at the end of which the key may be released by simply moving it forward to free the notch 502 from the edge of the keyboard plate and allow the key to be snapped up to normal position by its spring 503 (Fig. 4). The upper forward cam end of the lever 501 is adapted to cooperate with a stud 504 on the repeat slide 362 in such a manner that, when the key RN is depressed, it cams the slide 362 to its normal position of Fig. 4, if it is not already in such position, and holds the slide 362 in such position as long as the key RN remains depressed. When the carriage is in the "balance" columnar position, the roll 400 holds the lever 364 in a rearward position such that the slide 362 is yieldingly held in a rearward position where the upwardly extending forward end of the slide holds the latch 404 in releasing position and the slide 362 holds the member 352 with its shoulder 357 in the path of the stud 358. However, when the slide 362 is cammed back to the position of Fig. 4 by the lever 501 when the cycle normal key RN is depressed, the slide 362, through the stud 378 engaging in the slotted end of the arm 377, returns the latter arm and arm

378 to the position of Fig. 4, removing the latter arm away from the stud 378.

If the operator now depresses the cycle normal key RN and latches it in depressed position, moves the subtract lever S to the position corresponding to the sign of the balance in the crossfooter and depresses the regular motor bar M to give the machine a spacing cycle of operation, the crossfooter is tumbled and the bail 470 is moved to withdraw the lateral lug 481 from beneath the end of arm 482 during the forward stroke of the spacing cycle so that, at the beginning of the return stroke of this spacing cycle, the hooked end of the latch arm 483 is moved out of the path of the stud 484. However, during the forward stroke of this spacing cycle, the lever 405 is relatched above the hook 404 of the latch yoke 402 which was permitted to return to latching position when the repeat slide 362 was cammed forward by depression of the key RN. Therefore, a balance printing cycle of the machine will not be initiated automatically at the end of the spacing cycle. During the return stroke of the spacing cycle, the regular motor bar is released and permitted to return to normal because the forward movement of the repeat slide 362 by depression of the key RN also moved the upper end of the arm 378 forward and the member 352 was permitted to move clockwise in Fig. 4 until its stud 351 engaged against the lower rear cam edge of the finger 359 of the stem of the upper motor bar U which, during said spacing cycle, is in its normal upper position. Thereby, the notch 355 was placed in the path of the stud 358 and both pawls 57 and 58 were permitted to pass the roller 60 during the forward stroke of the spacing cycle and to act on said roller during the return stroke of the cycle to release the repeat hook 38 from the stud 39. The machine, therefore, comes to rest at the end of the spacing cycle and the carriage remains in the same columnar position because of the automatic disablement of the tabulating mechanism as previously explained. If, now, the operator releases the repeat normal key RN and permits it to return to its normal upward position, the cam lever 501 frees the slide 362, which is thereupon moved rearward by the spring 373 until the forward end of the slot in said slide 362 engages against the stud 383 in the lever 364 which is held in its rearward position by the roll 400 on the carriage. This rearward movement of the slide 362 causes the upwardly extending forward end of said slide to move the latch 404 to release the automatic total mechanism which thereupon initiates an automatic balance printing cycle of the machine in the manner already described.

If the operator, at the time of entering the amount of a check in one of the check columns, in performing the kind of work illustrated in Fig. 20, is aware of the fact that the subtraction of the amount of the said check from the positive balance in the crossfooter will produce a negative or overdraft balance in the crossfooter, the operator may, if permitted by the practice of the bank, cause the overdrawn balance to be automatically printed in the balance column in a more direct and shorter manner, provided there is no item to be entered in the "deposit" column. To initiate the cycle for subtracting the amount of the check, the upper motor bar U may be depressed and manual pressure immediately withdrawn. Then the operator may manually hold the subtract lever S in the subtract position when

the carriage tabulates to the "deposit" columnar position as well as during the automatic cycle of operation which will be performed while the carriage is in the deposit columnar position. During the automatic cycle in the "deposit" column the crossfooter tumbling frame will remain in its — position because of the subtract lever S being held in the — position. Therefore, when the carriage tabulates into the first balance columnar position, the bail 470 will be in the position of Figs. 1 and 9 because the position of the crossfooter tumbling frame corresponds to the sign of the total in the crossfooter and the roll 400 on the carriage will cause the release of the automatic total mechanism by which a balance printing cycle of the machine will be automatically initiated while the operator still holds the subtract lever S in the — position. If the operator permitted the lever S to return to the + position under the influence of the spring 235 before the total key bell crank 270 is rocked to total-taking position, said bell crank would become locked by the previously mentioned interlock and the balance printing cycle would be blocked until the operator manually returned the subtract lever to the — position. After the total key bell crank has been rocked to total-taking position, however, the operator may release the lever S, which is held in the usual way against movement while the total key remains depressed. It will be recalled that the total key bell crank 270 remains in the total taking position continuously from the start of the subtotal-taking operation with the carriage in the column 5 position in the example of work illustrated in Fig. 20 until the end of the total-taking operation in column 6.

Presetttable selective carriage return

The machine is provided with improved means adapted to be preconditioned or preset when the machine is operated with the paper carriage in a predetermined position, which corresponds to a column on the work sheet for entries the presence or absence and/or character of which determines what or whether any entries are to be made with the carriage in a nonadjacent subsequent columnar position or positions, to cause the carriage to be returned directly from an intermediate columnar position when no entries are to be made with the carriage in said subsequent columnar position and to permit said carriage to tabulate into said subsequent columnar position when required for entries. For that purpose advantage is taken of the fact that, with the carriage in the above-mentioned predetermined columnar position, such as the column 4 position for the example of work illustrated in Fig. 20, the machine cycle may be performed either with the upper motor bar U depressed to cause the skip bail 343 to be lowered without, however, causing a skip tabulation of the carriage if a skip release member 348a—349a is positioned to act before the carriage reaches the next columnar position, or as a result of depressing the regular motor bar M without lowering the skip bail.

It will be remembered that when the carriage tabulates into its final columnar position, the column 7 position for the example of Fig. 20, the control member 204 on the carriage, acting on the slide 196, conditions the bell crank 202 and the pawl 210 to cause the carriage return clutch to be engaged by depression of the link 208 during the latter part of the machine cycle initiated

with the carriage in that position. The slide 196 also has a lug 510 (Figs. 13 and 16) which, under certain conditions, may be engaged by a projection 511 (Figs. 15 to 18) of a presettable control means on the carriage to move the slide 196 to condition the bell crank 202 and pawl 210 to cause the carriage return clutch to be engaged in a machine cycle performed with the carriage in a preceding columnar position, the column 6 position for the example of Fig. 20. The control projection 511 extends rearwardly from the lower transverse part of a generally U-shaped member 512 (Figs. 17 and 18) pivoted at the upper ends of its vertical side arms on a stud 513 secured in the side portions of a frame member 514. The side members of the frame 514 are mounted at their lower ends on the shaft 344 which passes through openings therein, and are notched at their upper ends to embrace a shaft 515 supported in the side members of the paper carriage frame. The frame 514 is adjustably secured in the desired position lengthwise of the carriage by collars 516 adjustably secured on the shaft 344 between the side members of the frame 514. A second generally U-shaped member 517 is also pivoted on the stud 513 at the upper ends of its vertical side arms, one of which carries a stud 518 against which one side arm of the member 512 is yieldingly held by a spring 519 (Fig. 18) connected between said stud 518 and a lug 520 on the forward edge of the transverse portion of the member 512. A spring 521 connected between the stud 518 and the transverse front portion of the frame member 514 yieldingly urges the lug 520 against said portion of the frame member 514. A yoke member 522 also pivoted on the stud 513 has a lower notched arm 523 embracing the stud 518 to cause the member 517 and yoke 522 to rock in unison on the stud 513, and an upper arm 524 extending rearwardly over the skip bail 343. While the parts 511—524 are in their normal condition as shown in Fig. 18, the path of the end of the projection 511 is forward of lug 510 of the slide 196 and projection 511 is ineffective to condition the slide 196 to cause a return movement of the carriage.

A clip 525 (Figs. 15 and 19) longitudinally slidably mounted on the bail 343, carries a stud 526 on which a latch pawl 527 is pivoted. A spring 528 connected between the tail of the pawl 527 and a stud 529 carried by a clip 530 adjustably secured on the bail 343 and similar to the clips 349 and 349a, normally yieldingly holds the pawl 527 in the normal position of Fig. 19 and normally yieldingly holds the slidable clip 525 in engagement with the clip 530. A stud 531 (Fig. 15) secured in the clip 525 projects through an aperture in the pawl 527 to limit the rocking of the latter on its pivot. The clip 530 is adjustably secured on the bail 343 at such a position that when the carriage comes to rest in the above mentioned predetermined columnar position, the column 4 position for the example of work illustrated in Fig. 20, and with the sliding clip 525 engaged against the clip 530, a stud 532 secured in the clip 525 will be slightly to the left, viewing the machine from the rear, of the left side vertical edge 534 of a member 533 (Fig. 15) secured on the top plate of the housing 132. If, while the carriage is in that position, a machine cycle is initiated by depression of the regular motor bar M, the bail 343 will be held in its normal upper position by the roller stud 342 on the slide 338 and the stud 532 will engage an inclined cam

edge 535 on the member 533 as the carriage tabulates near the end of the machine cycle, whereby the bail 343 will be momentarily elevated somewhat above its normal position as the stud 532 rides over the member 533 without the clip 525 being shifted out of contact with the clip 530. The condition of the parts 511-524 is not altered and the projection 511 remains ineffective to condition the slide 196 for a return of the carriage prior to the engagement of the slide 196 by the control member 204.

If, with the carriage in the same position, the column 4 position for the example of Fig. 20, a machine cycle is performed with the upper motor bar U in its depressed condition, the slide 338 is depressed and latched down and the skip bail 343 is depressed by its spring 345 prior to tabulation of the carriage. The lowering of the bail 343 positions the stud 532 to engage the vertical edge 534 of the member 533 which, thus, holds the stud 532 and slideable clip 525 against moving with the carriage during the initial portion of its tabulating movement toward the next columnar position. The movement of the carriage causes a relative shifting of the clip 525 on the bail 343 and against the tension of the spring 528 and relative to the arm 524 until the arm 524 has passed a latch shoulder 536 on the upper edge of the pawl 527 as in Figs. 15 and 16, and the springs 528 and 521 cause the shoulder 536 and arm 524 to prevent the spring 528 from returning the slideable clip 525 into engagement with the clip 530. At this point in the tabulating movement of the carriage the stud 348a on the skip release clip 349a trips the latch 340 and the spring 339 restores the slide 338, roller 342 and bail 343 to their normal elevated positions, thus lifting the stud 532 above the vertical edge 534 of the member 533. The spring 528 then causes the stud 532 and clip 525 to move with the carriage, maintaining the latch shoulder 536 of the pawl 527 in latching engagement with the side edge of the end portion of the arm 524. As the stud 532 then rides up the inclined edge 535 and over the top of the member 533, the bail 343 is cammed upwardly and forwardly about the shaft 344 and the arm 524 is swung upwardly about the stud 513, the latch shoulder 536 of the pawl 527 sliding forwardly on the edge of the arm 524 until it registers with a notch 537 in the edge of the arm 524 and is pulled into said notch by the spring 528 whereby the parts are latched against downward movement of the arm 524 and bail 343 when the stud 532 has passed the member 533. Such lifting of the arm 524 swings the stud 518 rearwardly against the tension of the spring 521 so that the spring 519 rocks the member 512 to move its projection 511 rearwardly into a path which intersects the lug 510 on the slide 196. The parts remain latched in this position until the carriage reaches the subsequent position from which it is desired that the carriage should return after the above described mechanism has been thus preset. A clip 539 similar to the clips 349 and 349a is adjustably secured on the bail 343 in position to be engaged by a projection 538 of the slideable clip 525 to force the stud 532 over the cam end of the member 533 if the spring 528 should, unaided, fail to accomplish that.

For the example of work illustrated in Fig. 20, the projection 511 and lug 510 are so arranged that the former engages the latter as the carriage tabulates into the column 6 position and shifts the slide 196 sufficiently to position the lug 205 on the bell crank 202 in the path of the

upper arm of the bell crank 206 and causes the stud 207 to rock the bell crank 206 and depress the link 208 sufficiently to permit the pawl 210 to engage under the stud 156. Consequently, the carriage return clutch will be engaged when the stud 156 is depressed after the printing operation in the automatic total-taking machine cycle performed with the carriage in the column 6 position. Thus, because of the upper motor bar U being in depressed condition during the machine cycle performed with the carriage in a predetermined columnar position, the column 4 position for the example of Fig. 20, the carriage is returned automatically in the latter portion of a machine cycle performed with the carriage in a columnar position intermediate said predetermined columnar position and a nonadjacent subsequent columnar position instead of tabulating into said subsequent columnar position after the operation with the carriage in said intermediate columnar position as it would if the cycle with the carriage in said intermediate columnar position had been performed with the upper motor bar U in its normal position. The control member 215, 218 disconnects the return clutch, as previously described, after the carriage has been returned slightly past its column 1 position.

During the return of the carriage resulting from the action of the projection 511 on the lug 510, the preset parts of the mechanism of Figs. 15 to 18 are restored to normal. The rack 130 is mounted on the carriage by headed studs which are carried by brackets 540 (Fig. 19) secured on the rack and project through horizontal slots in brackets 541 secured on the carriage frame. The rack 130 is normally held at the right-hand limit of its movement relative to the carriage, as viewed from the rear, by a spring 542. The rack 130 also carries a downwardly extending projection 545 (Figs. 15 and 19) which is normally engaged by a stud 546 on one arm of a bell crank 547 which is pivoted on a stud 548 secured on the carriage frame. A link 549 pivoted on the other arm of the bell crank has a hooked lower end engaging under a stud 550 secured in a plate 551 secured on the shaft 344 and carrying a stud 552 connected with a spring 553 which urges the plate clockwise in Fig. 15 and holds the stud 546 in engagement with the projection 545. The stud 552 also passes through a cam slot in an arm 554 secured to the shaft 515 to which is also secured an arm 555. When the carriage return clutch is engaged, the rack 130 is moved leftward relative to the carriage, as viewed from the rear, before moving the carriage in the return direction. During such movement of the rack 130 relative to the carriage, the projection 545, acting on the stud 546, rocks the bell crank 547 to lift the link 549 and rock the plate 551 counterclockwise in Fig. 15, thereby rocking the arm 554 and shaft 515 clockwise and causing the rear end of the arm 555 to engage a lug 556 of the latch pawl 527 and rock said pawl counterclockwise to disengage its shoulder 536 from the arm 524. Thereupon the spring 528 slides the clip 525 rightward into engagement with the clip 530, and the spring 521 is permitted to return the arm 524 and member 512 with its projection 511 to normal as soon as the bail 343 returns to normal. An arm 557 secured on the shaft 344 carries a stud 558 which engages the arm 346 of the skip bail 343 to hold the bail 343 above its normal position during the return of the carriage which also facilitates unlatching of the arm 524 and pawl 527.

The movement of the rack 130 relative to the carriage when the carriage return clutch is engaged also causes operation of the usual line-spacing mechanism in a well-known manner, as disclosed in the Rinsche Patent No. 1,580,534 or as disclosed in my prior application Serial No. 424,970 filed December 30, 1941.

Lines II and III of the example of work in Fig. 20 illustrate the return of the carriage from the column 6 position, without tabulation into the column 7 position, because of the presetting of the mechanism of Figs. 15 and 16 in consequence of the upper motor bar U being depressed for the column 4 operation in line II and depressed for the column 3 operation and remaining latched down in the column 4 operation in line III. In lines I and IV, the carriage tabulates into the column 7 position because of the mechanism of Figs. 15 and 16 remaining in normal condition in consequence of the machine operations in column 4 in both lines being initiated by depression of the regular motor bar, notwithstanding depression of the upper motor bar U for a previous operation in column 1 of line IV.

While Fig. 20 shows schematically a particular set-up of the automatic carriage controls suited for the example of work there illustrated, it will be appreciated that the adjustability of the various parts permits the control set-up to be arranged to suit other work which may be required to be performed by the machine.

While operation of the machine when the paper carriage is in its final columnar position will ordinarily cause an automatic return of the carriage, the carriage may be caused to remain in such position by initiating the machine cycle by depressing the lower motor bar L and maintaining manual pressure thereon during the cycle. In each machine cycle initiated by depression of the lower motor bar L, the roller stud 119a on the slide 118 is depressed. The stud 119a overlies the upper edge of the lever 331 and depresses the latter to such an extent that the stud 329 is cammed into the upper rear corner of the cam slot 330, thereby rocking the lever 147 counterclockwise and levers 148 and 151 clockwise and depressing the stud 212 sufficiently to return the pawl 210 to its ineffective position even if the link 208 has been lowered by movement of the slide 196 by the carriage return control member 294. Therefore, the stud 156 will not act on the link 208 to cause the carriage to be returned to its column 1 position during any machine cycle initiated by depression of the lower motor bar L. The depression of the rear end of lever 151 by the action of the roller stud 119a on the cam lever 331 is not sufficient to cause the stud 152 to position the hooked end of the pawl 153 under the stud 156 so that, if manual pressure is maintained on the lower motor bar during the cycle, the carriage will remain stationary, but if manual pressure is withdrawn from said motor bar immediately after depression, the stud 145 will rock the levers 147, 149 and 151 further to enable the pawl 153 to be effective to cause depression of the link 154 and cause a return of the carriage to the columnar position determined by the position of the control roll 179 as previously described. It will also be clear that, if the set-up of the carriage controls did not cause automatic cycling of the machine when the carriage reached its column 6 position in Fig. 20, the lower motor bar L and mechanism controlled thereby would be effective to cause the carriage to remain in said column

for successive machine cycles or to return to the position determined by the control roll 179, depending upon the manner of manipulation of the lower motor bar, regardless of whether or not the presettable carriage return control means of Figs. 15-18 were or were not preset for automatic return of the carriage from the column 6 position but would not alter the condition of the presettable control means, whether preset or not, unless the carriage were returned and the rack 130 shifted on the carriage to actuate the bell crank 547. It is thus possible to make a succession of vertically spaced entries with the carriage in any columnar position where the machine is not automatically cycled.

The presettable carriage return means may also be manually conditioned, when and for as long as desired, to prevent tabulation of the carriage beyond the columnar position where the projection 511, when in effective position, can act on the lug 510. For this purpose, a manual shift lever 560 (Fig. 19) pivoted on a stud 561 in a bracket 562 mounted on the carriage is connected with a link 563 notched to cooperate with a latch member 564 to releasably latch the lever 560 in any of a plurality of adjusted positions. The link 563 is in turn connected to a slide 565 slidably mounted on studs 566 on the carriage. The slide 565 is in turn connected with a slide 568 also slidably mounted on the carriage. The slide 568 carries one or more studs 578 which, when the lever 560 is adjusted to certain positions, act on a lower cam portion 571 of the member 517 to cam the latter and thereby also the projection 511 rearwardly into position to act on the lug 510 each time the carriage tabulates into the columnar position determined by the location of the parts 511 and 510, the column 6 position in the example of Fig. 20. While the lever 560 remains in such position of adjustment, the carriage return clutch will be engaged in each cycle of operation of the machine performed while the carriage is in such columnar position, the column 6 position in the example of Fig. 20, excepting machine cycles which are initiated by depressing the lower motor bar L and manually holding it down to prevent stud 145 from acting on lever 146. In cycles effected in the last-described manner, the carriage will remain stationary. In any event the carriage will not tabulate beyond a columnar position for which a stud 578 is provided, while the lever 560 remains in the position of adjustment to render the stud 578 effective.

The slide 565 may also operate a rack 589 meshing with pinions 575 adapted, in a well-known manner, to vary the adjustment of eccentrically mounted control rolls or of disks with control lobes of differing lengths whereby the shifting of the lever 560 will also result in changes of programs of carriage controlled machine functions as well as variations of carriage movements.

It will be appreciated that, by providing a plurality of cam members 533 in positions to act on the stud 532 in different positions of the carriage, the presetting of the parts 511-536 may be effected under control of the upper motor bar U in a plurality of different columnar positions of the carriage.

While the specific construction and embodiment of the invention heretofore described in connection with and illustrated in the accompanying drawings is particularly well adapted for the performance of the example of work illustrated in Fig. 20 as well as many other varieties of work, it is to be understood that the invention is not lim-

ited to the specific construction and arrangement of parts and mechanisms described and illustrated but is also capable of embodiment in various other forms and arrangements within the scope of the appended claims.

I claim:

1. A machine of the class specified having a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means, and means controlled by said carriage and, when said carriage is in a predetermined nonadjacent preceding columnar position, rendered presettable by said presetting means to enable it to condition said control means to render said carriage return means effective when said carriage is in a columnar position intermediate said preceding and final columnar positions.

2. A machine of the class specified having a traveling carriage movable to a plurality of columnar positions, means to tabulate said carriage in one direction, power-operated means to return said carriage in the opposite direction, control means to render said return means effective to return said carriage, means on said carriage to condition said control means to render said return means effective when said carriage is in its final columnar position in the direction of its tabulating movement, presetting means, and means on said carriage rendered presettable by said presetting means, when said carriage is in a predetermined nonadjacent preceding columnar position, to enable it to condition said control means to render said carriage return means effective when said carriage is in a columnar position intermediate said preceding and final columnar positions.

3. A machine of the class specified having a traveling carriage movable to a plurality of columnar positions, means to tabulate said carriage in one direction from each columnar position to the next, skip means including a carriage-supported control means conditionable to cause said carriage to skip through a predetermined columnar position in its movement in the tabulating direction, power-operable means to return said carriage in the opposite direction, means controlled by said carriage to condition said carriage return means, when said carriage is in a final position, to return said carriage, and means on said carriage automatically preset under control of said carriage-supported skip control means when the latter is in skip condition and said carriage is in a predetermined, nonadjacent, preceding columnar position, to condition said return means when said carriage is in a columnar position intermediate said preceding and final columnar positions, to return said carriage.

4. A machine of the class specified having a traveling carriage movable to a plurality of columnar positions, means to tabulate said carriage in one direction from each columnar position to the next, skip means including a carriage-supported control means conditionable to cause said carriage to skip through a predetermined columnar position in its movement in the tabulating direction, power-operable means to return said carriage in the opposite direction, means

controlled by said carriage to condition said carriage return means, when said carriage is in a final position, to return said carriage, and means on said carriage and automatically presettable under control of said carriage-supported skip control means when the latter is in skip condition when said carriage is in a predetermined, nonadjacent, preceding columnar position, to condition said return means when said carriage is in a columnar position intermediate said preceding and final columnar positions, to return said carriage.

5. A machine of the class specified having means to drive it through cycles of operation, a carriage movable to a plurality of columnar positions, means to move said carriage in one direction, means normally effective, upon movement of said carriage in the tabulating direction from each of said columnar positions, to arrest said carriage in the next columnar position, skip means including a carriage-supported skip control means conditionable to disable said arresting means, power-operated means to return said carriage in the opposite direction, means controlled by said carriage to condition said return means, in a machine cycle when said carriage is in a final columnar position, to return said carriage, means on said carriage and presettable under control of said carriage-supported skip control means when the latter is in skip condition when said carriage is in a predetermined, nonadjacent, preceding columnar position, to condition said return means, in a machine cycle when said carriage is in a columnar position intermediate said preceding and final columnar positions, to return said carriage, and means on said carriage to re-enable said arresting means prior to the arrival of said carriage in said intermediate columnar position in its movement in the tabulating direction from said preceding columnar position.

6. A machine of the class specified having a power drive means, a plurality of manipulative means for causing said drive means to drive said machine through cycles of operation, a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means controlled by a predetermined one of said manipulative means, and means controlled by said carriage rendered presettable by said presetting means, when said carriage is in a predetermined nonadjacent preceding columnar position in a machine cycle caused by manipulation of said predetermined one of said manipulative means, to enable said presettable carriage-controlled means to condition said control means to render said carriage return means effective when said carriage is in a columnar position intermediate said preceding and final columnar positions.

7. A machine of the class specified having a power drive means, a plurality of manipulative means for causing said drive means to drive said machine through cycles of operation, a traveling carriage movable to a plurality of columnar positions, means to tabulate said carriage in one direction from each columnar position to the next, skip means including a carriage-supported control means conditionable under control of a pre-

determined one of said manipulative means, when manipulated to initiate a machine cycle, to cause said carriage to skip through a predetermined columnar position in its movement in the tabulating direction, power-operable means to return said carriage in the opposite direction, means controlled by said carriage to condition said carriage return means, when said carriage is in a final position, to return said carriage, and means on said carriage automatically preset under control of said carriage-supported skip control means when the latter is in skip condition and said carriage is in a predetermined, nonadjacent, preceding columnar position, to condition said return means when said carriage is in a columnar position intermediate said preceding and final columnar positions to return said carriage.

8. A machine of the class specified having a power drive means, a plurality of manipulative means for causing said drive means to drive said machine through cycles of operation, a traveling carriage movable to a plurality of columnar positions, means to tabulate said carriage in one direction from each columnar position to the next, skip means including a carriage-supported control means conditionable under control of a predetermined one of said manipulative means, when manipulated to initiate a machine cycle, to cause said carriage to skip through a predetermined columnar position in its movement in the tabulating direction, power-operable means to return said carriage in the opposite direction, means controlled by said carriage to condition said carriage return means, when said carriage is in a final position, to return said carriage, and means carried on said carriage and automatically presettable under control of said carriage-supported skip control means when the latter is in skip condition when said carriage is in a predetermined, nonadjacent, preceding columnar position, in a machine cycle caused by manipulation of said predetermined one of said manipulative means, to condition said return means when said carriage is in a columnar position intermediate said preceding and final columnar positions to return said carriage.

9. A machine of the class specified having a power drive means, a plurality of manipulative means to cause said drive means to drive said machine through cycles of operation, a carriage movable to a plurality of columnar positions, means to move said carriage in one direction, means normally effective, upon movement of said carriage in the tabulating direction from each of said columnar positions, to arrest said carriage in the next columnar position, skip means including a carriage-supported skip control means conditionable under control of a predetermined one of said manipulative means, when manipulated to initiate a machine cycle, to disable said arresting means, power-operated means to return said carriage in the opposite direction, means controlled by said carriage to condition said return means, in a machine cycle when said carriage is in a final columnar position, to return said carriage, means on said carriage and presettable under control of said carriage-supported skip control means when the latter is in skip condition when said carriage is in a predetermined, nonadjacent, preceding columnar position in a machine cycle caused by manipulation of said predetermined one of said manipulative means, to condition said return means, in a machine cycle when said carriage is in a columnar position intermediate said preceding and final co-

lumnar positions to return said carriage, and means on said carriage to re-enable said arresting means prior to the arrival of said carriage in said intermediate columnar position in its movement in the tabulating direction from said preceding columnar position.

10. A machine of the class specified having means to drive it through cycles of operation, a traveling carriage movable to a plurality of columnar positions, means to tabulate said carriage in one direction, power-operated means to return said carriage in the opposite direction, a member moved by said drive means in each machine cycle, control means to enable said moved member to render said return means effective to return said carriage, means controlled by said carriage to condition said control means to enable said moved member to render said return means effective in a machine cycle performed when said carriage is in its final columnar position in the direction of its tabulating movement, presetting means, and means controlled by said carriage and, when said carriage is in a predetermined nonadjacent preceding columnar position, thereby rendered presettable by said presetting means to enable it to condition said control means to enable said moved member to render said carriage return means effective when said carriage is in a columnar position intermediate said preceding and final columnar positions.

11. A machine of the class specified having means to drive it through cycles of operation, a traveling carriage movable to a plurality of columnar positions, means to tabulate said carriage in one direction from each columnar position to the next, skip means including a carriage-supported control means conditionable to cause said carriage to skip through a predetermined columnar position in its movement to the tabulating direction, power operable means to return said carriage in the opposite direction, a member moved by said drive means in each machine cycle, means controlled by said carriage to enable said moved member to condition said carriage return means, when said carriage is in a final position, to return said carriage, and means on said carriage automatically preset under control of said carriage-supported skip control means when the latter is in skip condition and said carriage is in a predetermined, nonadjacent, preceding columnar position, to enable said moved member to condition said return means when said carriage is in a columnar position intermediate said preceding and final columnar positions to return said carriage.

12. A machine of the class specified having a power drive means, a plurality of manipulative means for causing said drive means to drive said machine through cycles of operation, a traveling carriage movable to a plurality of columnar positions, means to tabulate said carriage in one direction, power-operated means to return said carriage in the opposite direction, a member moved by said drive means in each machine cycle, control means to enable said moved member to render said return means effective to return said carriage, means controlled by said carriage to condition said control means to enable said moved member to render said return means effective when said carriage is in its final columnar position in the direction of its tabulating movement, presetting means controlled by a predetermined one of said manipulative means, and means controlled by said carriage rendered

presetable by said presetting means, when said carriage is in a predetermined nonadjacent preceding columnar position in a machine cycle caused by manipulation of said predetermined one of said manipulative means, to enable said presettable carriage-controlled means to condition said control means to enable said moved member to render said carriage return means effective when said carriage is in a columnar position intermediate said preceding and final columnar positions.

13. A machine of the class specified having a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means, normally ineffective means controlled by said carriage and, when said carriage is in a predetermined nonadjacent preceding columnar position, rendered presettable by said presetting means to enable it to condition said control means to render said carriage return means effective when said carriage is in a columnar position intermediate said preceding and final columnar positions, and means rendered operative by said return means, when operated to return said carriage to restore said preset means to normal condition.

14. A machine of the class specified having a traveling carriage movable to a plurality of columnar positions, means to tabulate said carriage in one direction from each columnar position to the next, skip means including a carriage-supported control means conditionable to cause said carriage to skip through a predetermined columnar position in its movement in the tabulating direction, power-operable means to return said carriage in the opposite direction, means controlled by said carriage to condition said carriage return means, when said carriage is in a final position, to return said carriage, means on said carriage automatically preset under control of said carriage-supported skip control means when the latter is in skip condition and said carriage is in a predetermined, nonadjacent, preceding columnar position, to condition said return means when said carriage is in a columnar position intermediate said preceding and final columnar positions to return said carriage, and means actuated by said carriage return means, as the latter operates to return said carriage, to restore said preset means to its normal condition.

15. A machine of the class specified having a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means, normally ineffective means controlled by said carriage and, when said carriage is in a predetermined nonadjacent preceding columnar position, rendered presettable by said presetting means to enable it to condition said control means to render said carriage return means effective

when said carriage is in a columnar position intermediate said preceding and final columnar positions, and means to retain said presettable means in preset condition when preset, said retaining means being operable by said return means, when the latter operates to return said carriage, to release said presettable means.

16. A machine of the class specified having a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means, means controlled by said carriage and, when said carriage is in a predetermined nonadjacent preceding columnar position, rendered presettable by said presetting means to enable it to condition said control means to render said carriage return means effective when said carriage is in a columnar position intermediate said preceding and final columnar positions, and means controlled by said carriage for automatically causing said drive means to drive said machine through a cycle of operation when said carriage arrives in said intermediate columnar position.

17. A machine of the class specified having a traveling carriage movable to a plurality of columnar positions, means to tabulate said carriage in one direction from each columnar position to the next, skip means including a carriage-supported control means conditionable to cause said carriage to skip through a predetermined columnar position in its movement in the tabulating direction, power operable means to return said carriage in the opposite direction, means controlled by said carriage to condition said carriage return means, when said carriage is in a final position, to return said carriage, means on said carriage automatically preset under control of said carriage-supported skip control means when the latter is in skip condition and said carriage is in a predetermined, nonadjacent, preceding columnar position, to condition said return means when said carriage is in a columnar position intermediate said preceding and final columnar positions, to return said carriage, and means controlled by said carriage for automatically causing said drive means to drive said machine through a cycle of operation when said carriage arrives in said intermediate columnar position.

18. A machine of the class specified having means to drive it through cycles of operation, a carriage movable to a plurality of columnar positions, means to move said carriage in one direction, means normally effective, upon movement of said carriage in the tabulating direction from each of said columnar positions, to arrest said carriage in the next columnar position, skip means including a carriage-supported skip control means conditionable to disable said arresting means, power-operated means to return said carriage in the opposite direction, means controlled by said carriage to condition said return means, in a machine cycle when said carriage is in a final columnar position, to return said carriage, means carried on said carriage-supported skip control means and automatically presettable when the latter is in skip condition when said carriage is in a predetermined, nonadjacent, preceding columnar position, to condition said return means.

in a machine cycle when said carriage is in a columnar position intermediate said preceding and final columnar positions, to return said carriage, means on said carriage to disable said skip means and re-enable said arresting means prior to the arrival of said carriage in said intermediate columnar position in its movement in the tabulating direction from said preceding columnar position, and means controlled by said carriage for automatically causing said drive means to drive said machine through a cycle of operation when said carriage arrives in said intermediate columnar position.

19. A machine of the class specified having a power drive means, a plurality of manipulative means for causing said drive means to drive said machine through cycles of operation, a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means controlled by a predetermined one of said manipulative means, means controlled by said carriage and rendered presettable by said presetting means, when said carriage is in a predetermined non-adjacent preceding columnar position in a machine cycle caused by manipulation of said predetermined one of said manipulative means, to enable said presettable carriage-controlled means to condition said control means to render said carriage return means effective when said carriage is in a columnar position intermediate said preceding and final columnar positions, and means controlled by said carriage for automatically causing said drive means to drive said machine through a cycle of operation when said carriage arrives in said intermediate columnar position.

20. A machine of the class specified having a power drive means, a plurality of manipulative means for causing said drive means to drive said machine through cycles of operation, a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means controlled by a predetermined one of said manipulative means, means controlled by said carriage and rendered presettable by said presetting means, when said carriage is in a predetermined non-adjacent preceding columnar position in a machine cycle caused by manipulation of said predetermined one of said manipulative means, to enable said presettable carriage-controlled means to condition said control means to render said carriage return means effective when said carriage is in a columnar position intermediate said preceding and final columnar positions, and means conditioned under control of said one of said manipulative means, when the latter is manipulated to initiate a machine cycle when said carriage is in a columnar position preceding said predetermined columnar position, to automatically cause said drive means to drive said machine through a further cycle of operation when said carriage arrives in said intermediate columnar position.

5   cally cause said drive means to drive said machine through a further cycle of operation when said carriage arrives in said predetermined columnar position and to enable said presetting means to preset said presettable means.

10   21. A machine of the class specified having a power drive means, a plurality of manipulative means for causing said drive means to drive said machine through cycles of operation, a traveling carriage movable to a plurality of columnar positions, means to tabulate said carriage in one direction, power-operated means to return said carriage in the opposite direction, control means to render said return means effective to return said carriage, means controlled by said carriage to condition said control means to render said return means effective when said carriage is in its final columnar position in the direction of its tabulating movement, presetting means controlled by a predetermined one of said manipulative means, means controlled by said carriage and rendered presettable by said presetting means, when said carriage is in a predetermined non-adjacent preceding columnar position in a machine cycle caused by manipulation of said predetermined one of said manipulative means, to enable said presettable carriage-controlled means to condition said control means to render said carriage return means effective when said carriage is in a columnar position intermediate said preceding and final columnar positions, means conditioned under control of said one of said manipulative means, when the latter is manipulated to initiate a machine cycle when said carriage is in a columnar position preceding said predetermined columnar position, to automatically cause said drive means to drive said machine through a further cycle of operation when said carriage arrives in said predetermined columnar position and to enable said presetting means, and means controlled by said carriage for automatically causing said drive means to drive said machine through a cycle of operation when said carriage arrives in said intermediate columnar position.

15   22. A machine of the class specified having a power drive means, a plurality of manipulative means for causing said drive means to give the machine cycles of operation, a traveling carriage movable to a plurality of columnar positions, carriage tabulating means normally operating in each cycle of machine operation to tabulate said carriage to the next columnar position in one direction, carriage return means for returning said carriage in the opposite direction, control means to render said carriage return means effective, means controlled by said carriage to condition said control means to render said carriage return means effective when the carriage is in a predetermined columnar position, means conditionable by one of said manipulative means when manipulated to initiate a machine cycle while the carriage is in a preceding columnar position to control said tabulating mechanism to cause said carriage to skip tabulate to a columnar position intermediate said preceding and predetermined columnar positions, and means conditionable by said manipulation of said one of said manipulative means and controlled by said carriage to cause said drive means to give the machine an automatic cycle of operation when said carriage reaches said intermediate columnar position, and means on said carriage presettable under control of said one of said manipulative means,

when manipulated to cause said automatic machine cycle to be performed, to condition said control means, when said carriage is in a columnar position between said intermediate and predetermined columnar positions, to render said carriage return means effective.

23. A machine of the class specified having a power drive means, a plurality of manipulative means for causing said drive means to give the machine cycles of operation, a traveling carriage movable to a plurality of columnar positions, carriage tabulating means normally operating in each cycle of machine operation to tabulate said carriage to the next columnar position in one direction, carriage return means for returning said carriage in the opposite direction, control means to render said carriage return means effective, means controlled by said carriage to condition said control means to render said carriage return means effective when the carriage is in a predetermined columnar position, means conditionable by one of said manipulative means when manipulated to initiate a machine cycle while the carriage is in a preceding columnar position to control said tabulating mechanism to cause said carriage to skip tabulate to a columnar position intermediate said preceding and predetermined columnar positions, means controlled by said carriage for automatically causing said cycling means to give the machine a cycle of operation when said carriage arrives in a columnar position between said intermediate and predetermined columnar positions, and means conditionable by said manipulation of said one of said manipulative means and controlled by said carriage to cause said drive means to give the machine an automatic cycle of operation when said carriage reaches said intermediate columnar position, and means on said carriage pre-settable under control of said manipulative means when manipulated to cause said automatic machine cycle to be performed while the carriage is in said intermediate columnar position to condition said control means to render said carriage return means effective in the automatic cycle of machine operation performed when said carriage is in said columnar position between said intermediate and predetermined columnar positions.

24. A machine of the class specified having a traveling carriage movable to a plurality of columnar positions, means to tabulate said carriage in one direction from each columnar position to the next, skip control means conditionable to cause said carriage to skip tabulate through columnar positions, power-operable means to return said carriage in the opposite direction, normally ineffective control means controlled by said carriage to be rendered potentially effective, when said carriage is in a predetermined position, to condition said return means to return said carriage, a common means to condition said skip control means for skip tabulation and to cause said carriage return control means, when potentially effective, to condition said return means to return said carriage, and means controlled by said carriage to restore said skip control means to non-skip condition when said common conditioning means has caused said return control means to condition said return means to return said carriage.

25. A machine of the class specified having means to drive said machine through cycles of operation, an element actuated from said drive means in machine cycles, a traveling carriage movable to a plurality of columnar positions,

means to tabulate said carriage in one direction to successive columnar positions in successive machine cycles, skip means to cause said carriage to skip tabulate through a number of columnar positions in a machine cycle, manipulative skip control means to place said skip means in skip tabulating condition, power operable means to return said carriage in the opposite direction, normally ineffective control means to render said return means effective to return said carriage, means controlled by said carriage to cause said normally ineffective control means to be actuated by said element in a machine cycle performed with said carriage in a predetermined columnar position to render said return means effective, means on said carriage rendered pre-settable under control of said skip control means when said carriage is in a columnar position preceding and non-adjacent to said predetermined columnar position to cause said normally ineffective control means to be actuated by said element to render said return means effective in a machine cycle performed with said carriage in an intermediate columnar position, and means controlled by said carriage to restore said skip means to non-skip condition prior to arrival of said carriage in said intermediate columnar position.

26. A machine of the class specified having means to drive said machine through cycles of operation, an element actuated from said drive means in machine cycles, a traveling carriage movable to a plurality of columnar positions, means to tabulate said carriage in one direction to successive columnar positions in successive machine cycles, skip means to cause said carriage to skip tabulate through a number of columnar positions in a machine cycle, manipulative skip control means to place said skip means in skip tabulating condition, power operable means to return said carriage in the opposite direction, normally ineffective control means to render said return means effective to return said carriage, means controlled by said carriage to cause said normally ineffective control means to be actuated by said element in a machine cycle performed with said carriage in a predetermined columnar position to render said return means effective, means on said carriage rendered pre-settable under control of said skip control means when said carriage is in a columnar position preceding and non-adjacent to said predetermined columnar position to cause said normally ineffective control means to be actuated by said element to render said return means effective in a machine cycle performed with said carriage in an intermediate columnar position, and means controlled by said carriage to restore said skip means to non-skip condition prior to arrival of said carriage in either of said preceding and intermediate columnar positions.

27. A machine of the class specified having means to drive said machine through cycles of operation, a traveling carriage movable to a plurality of columnar positions, means to tabulate said carriage in one direction to successive columnar positions in successive machine cycles, skip means to cause said carriage to skip tabulate through a number of columnar positions in a machine cycle, manipulative skip control means to place said skip means in skip tabulating condition, power operable means to return said carriage in the opposite direction, normally ineffective control means to render said return means effective to return said carriage, means controlled by said carriage to cause said control

means to render said return means effective in a machine cycle performed with said carriage in a predetermined columnar position, means on said carriage rendered presettable under control of said skip control means when said carriage is in a columnar position preceding and non-adjacent to said predetermined columnar position to cause said normally ineffective control means to render said return means effective in a machine cycle performed with said carriage in an intermediate columnar position, means controlled by said carriage to restore said skip means to non-skip condition prior to arrival of said carriage in either of said preceding and intermediate columnar positions, means conditionable by said skip control means when manipulated with said carriage in a columnar position ahead of said preceding columnar position to cause said drive means to drive said machine through an automatically initiated machine cycle upon arrival of said carriage in either of said preceding columnar position, and means controlled by said manipulative skip control means to retain the latter in manipulated condition during said automatically initiated cycle.

28. A machine of the class specified having means to drive said machine through cycles of operation, a traveling carriage movable to a plurality of columnar positions, means to tabulate said carriage to successive columnar positions in one direction in successive machine cycles, power operable means to return said carriage in the opposite direction, normally ineffective control means to render said return means effective, means controlled by said carriage to cause said control means to render said return means effective in a machine cycle performed with said carriage in a predetermined columnar position, a manipulative means, means on said carriage rendered presettable under control of said manipulative means when said carriage is in a columnar position preceding and non-adjacent to said predetermined columnar position to cause said normally ineffective control means to render said return means effective in a machine cycle performed with said carriage in a columnar position intermediate said predetermined and

preceding columnar positions, means conditionable by said manipulative means with said carriage in a columnar position ahead of said preceding columnar position to cause said drive means to drive said machine through an automatically initiated machine cycle upon arrival of said carriage in said preceding columnar position, and means conditionable by said manipulative means when manipulated with said carriage in said columnar position ahead of said preceding columnar position to retain said manipulative means in presetting condition during said automatic machine cycle.

29. A machine of the class specified having means to drive said machine through cycles of operation, an element actuated from said drive means in machine cycles, a traveling carriage movable to a plurality of columnar positions, means to tabulate said carriage in one direction to successive columnar positions in successive machine cycles, power operable means to return said carriage in the opposite direction, normally ineffective control means to render said return means effective to return said carriage, means controlled by said carriage to cause said control means to be actuated by said element in a machine cycle performed with said carriage in a predetermined columnar position to render said return means effective, skip means to cause said carriage to skip tabulate through a number of columnar positions in a machine cycle, manipulative skip control means to place said skip means in skip tabulating condition, means positioned on said carriage to be rendered presettable by said skip control means when said carriage is in a columnar position preceding and non-adjacent to said predetermined columnar position to cause said normally ineffective control means to be actuated by said element in a machine cycle performed with said carriage in an intermediate columnar position, and means controlled by said carriage to restore said skip means to non-skip condition prior to arrival of said carriage in either of said preceding and intermediate columnar positions.

ROBERT L. MULLER.
